UNITED STATES PATENT OFFICE

JOHN ROYDEN PEIRCE, OF NEW YORK, N. Y., ASSIGNOR TO INTERNATIONAL BUSINESS MACHINES CORPORATION, OF NEW YORK, N. Y., A CORPORATION OF NEW YORK

ACCOUNTING MACHINE

Application filed December 24, 1923. Serial No. 682,365.

This invention relates to tabulating machines adapted to gather numerous items of information from stacks of record sheets and to formulate reports from the data thus gathered by printing the same in appropriate columns on a report sheet.

In machines of this kind it has heretofore been customary to list upon the report sheet certain items taken from record cards and to print totals of statistical data on the same or a separate sheet. The scope of operations of such machines, however, has been comparatively limited.

The object of the present invention is to produce a tabulating machine adapted to make out reports of more complicated kinds.

Thus, the present machine is adapted to analyze perforated record cards, taking the information therefrom and printing it upon a report sheet in separate columns according to the classification of the data; listing credit items in a credit column and debit items in a debit column, and adding such items to or subtracting them from balances brought forward from previous reports. The machine will also print the data relating to the credit and debit items under numerous separate headings according to various subclassifications of such items.

Accounting machines controlled by record cards and in which positive and negative entries were made by the machine have heretofore been proposed. In some machines such positive or negative entry was entered in one or the other of a pair of accumulators according to a designation on a record. In other machines attempts were made to take care of balances but in such machines the determination of the balance was effected by comparing an entry from the card with a previous balance which was retained in the machine not upon an accumulator but upon a perforated record. The machine obtained a running balance by such comparison of perforated records.

In the present machine, for the first time provision is made for entering items from records into separate accumulators as debits and credits and also into a common accumulator which takes either positive or negative

entries. This common accumulator therefore must be arranged not only to add numbers in the usual way but to subtract numbers which are representative of negative amounts. Amounts are entered as direct numbers into the positive accumulator or accumulators and into the balance accumulator and for negative numbers provision is made for reading the direct number upon the record, then converting the direct number into a complementary amount and this complementary amount is entered into the negative accumulators and into the balance accumulator which has received the direct entry of positive amounts. The conversion of the direct number into its complement is made intermediate the card reading devices and the accumulator. Provision is also made for printing the amounts standing on the several accumulators. Inasmuch as amounts may stand on some accumulators in the form of complements provision is made for printing not the complement amount on the printed record but a direct number amount which is the complement of a complement.

In handling complementary entries provision must be made to take care of the so-called elusive one. This is automatically done in the present machine by providing means for adding an additional step or increment of movement to the accumulator pinion when a complementary amount is entered. The extra unit is introduced only to the first denominational order of the accumulator and this is all effected automatically under card control.

In the handling of elusive or fugitive ones as they are sometimes called various considerations arise. On the accumulator which receives entries of complementary quantities only it is not only necessary to enter the quantities properly into the accumulator, but provision must be made for taking the proper amount out of the accumulator after the addition has been made. This necessitates reading out a complement of a complement from the accumulator. Where complements are entered into an accumulator and a complement of the total taken from the accumulator elusive ones must be added both on the entry of amounts

55

60

65

70

75

80

85

90

95

100

and upon the reading out of an amount. To avoid the necessity of taking the elusive one into consideration when reading out the quantity from the accumulator I modify the 5 entry of the elusive ones into the accumulator. This is done by omitting the entry of the elusive one for the first complementary entry and for thereafter automatically entering the elusive one for each complementary quantity. This is all done automatically under 10 card control and by the arrangement used the reading out of the quantity and converting it into its complement is materially simplified. On the balance accumulator, on the other 15 hand, inasmuch as the amount which is read out of the accumulator in the present machine is always a positive quantity it is not necessary to convert any complementary reading into a complement thereof in reading the 20 amount out. From the balance counter the machine always reads out the direct quantities standing thereon. Therefore in entering the complementary quantities into the balance counter the elusive one is entered for each 25 complementary quantity entered and there is no initial suppression of the entry of the elusive one as in the negative accumulator above described. The entering of the elusive one is effected automatically by the operation 30 of the machine and under card control as before.

Provision is made for reading the amount to be entered upon the accumulating device or devices from a common card field irrespective of the negative or positive character of the amount. Special controlling perforations determine the algebraic character of the amount. The invention, however, in its broader aspects is not limited to reading the 40 positive and negative amounts from a common field.

Provision is also made for controlling the distribution of entries to a plurality of accumulators. This is controlled not only in 45 accordance with the algebraic character of the entry itself but also in accordance with the particular class of the record so that there is a dual control of the distribution of items.

Referring to the drawings wherein I have 50 shown what I now consider to be the preferred form of my invention:

Fig. 1 is a perspective view of the machine.

Fig. 2 is a view of a card containing data 55 relating to an insurance policy, and adapted to control the operation of the machine.

Fig. 3 is a view of a balance card also adapted to control the machine.

Fig. 4 is a diagram showing the combinations of perforations used to designate the 60 several digits.

Figs. 5 and 6 are views of two forms of reports which the machine is adapted to make out.

65 Figs. 7 to 7d are portions of cards repre-

senting different conditions of insurance policies and adapted to control the machine differently.

Fig. 8 is a diagram showing the combinational arrangement of perforations used to 70 designate the sex of the insured, and whether the amount of insurance is to be added or not to predetermined counters in the machine, etc.

Fig. 9 is a diagrammatic view representation of the manner in which cards representing 75 various conditions control the machine differently.

Fig. 10 is a plan view of the machine, portions of the covering being broken away to 80 show hidden elements.

Fig. 11 is a sectional plan view of the main carry box and the finder.

Fig. 12 is a front elevation of the main portion of the machine with the covering removed.

Figs. 94 and 94a are details in different positions of mechanism for feeding paper into position in the machine.

Figs. 95 and 95a are views of signalling 15 mechanism controlled by the printing of a predetermined number of lines of items.

Fig. 96 is a detail of the signal bell and operating connections.

Fig. 97 is a view taken at right angles to 20 Fig. 96 of the bell.

Fig. 98 is a timing diagram.

As an example of the work that the machine will perform I have illustrated several cards adapted for use in connection with an insurance business. For each policy issued, revived, discontinued or changed, a card 10, Fig. 2 may be filled out. The card is shown as divided into upper rows 11, 12 of fields 13, 14, etc., separated by vertical lines 15. The 25 fields have printed therein a designation of the statistics contained within that particular field. Thus, the field 13 is for the policy number. This number is inserted by the use of a machine such as that disclosed in my co-pending application, Serial No. 566,447. The lower half of the card contains two rows 11a and 12a of fields 13a, 14a, etc., also divided by vertical lines. The fields 13a and 14a are in turn divided into columns of imaginary 30 squares corresponding to the squares shown in Fig. 4. These squares comprise hole spaces or spaces adapted to receive perforations. There are four hole spaces to each column, and one or two holes may be punched in each 40 column to represent a digit according to the combination arrangements illustrated in Fig. 4. When the printing of figures is effected in one of the fields in the upper half of the card, holes are punched in the corresponding 45 field in the lower half of the card. Thus, in printing the policy number on a machine of the type shown in the aforesaid application, when the digit "8" is printed, two holes will be perforated in the first column of hole 50 spaces in field 13a which is directly under the digit "8". These holes in the positions 55 represent the digit "8" according to the tables in Fig. 4. Similarly for all of the other digits of the policy number and of the other figures 60 in the upper rows 11, 12, the proper perforations appear in the corresponding column of hole spaces in the lower rows 11a, 12a respectively.

A report such as required by insurance companies and which the present machine is ca-

pable of formulating is illustrated in Fig. 5. This report shows the summary of the insurance in force. At stated periods, as for instance once a month, or whenever desired a revised report may be made out by running 70 the new card through the machine along with balance cards showing what is contained in the old report.

In Fig. 2 the field 16 shows the year in which the insurance was issued, in the present 75 instance being 14 meaning 1914. The field 17 contains a number designating the kind of insurance represented by the card. Before running the cards through the tabulator they are sorted into groups, in the present instance 80 according to year and kind, so that all cards for a particular year are in one group followed by those for the next year. And all those for each year are in successive sub-groups according to kind.

If a policy issued in 1913 is, during a subsequent year, changed to a different kind, or is discontinued, or having been discontinued is revived, a card 10 is filled out accordingly, but the policy remains a 1913 policy.

As indicated on the first line of the report, Fig. 5, the machine analyzes all cards for 90 1913 of kind 25,630; counts the policies existing; totals the amount of insurance existing; counts the revived policies and totals the 95 amount of insurance involved therein; the number of policies of that year that have been changed to or from that kind, etc., and prints the results. Policies for the same year of different kinds are in turn treated in the same 100 manner. After all 1913 policies have been taken, and before commencing with those for 1914, the machine may print the total number of policies for 1913 still in existence and the total amount of insurance represented 105 thereby. As shown, sub-totals may be printed from time to time of the figures that have gone before.

It is not necessary for all cards to be run through the tabulating machine each time a 110 report is to be made out. Instead, balance cards may be used. Such a card is shown at 18 in Fig. 3.

After the report has been made, a card 18 may be made out covering the valuation in 115 force for the various ages under the heading of kind and year. These cards are kept in their proper order and as new cards such as card 10 are made out they may be placed with the balance cards; those relating to a given 120 age under a particular kind and year being placed next to the balance card of that age, kind and year. When these cards are run through the tabulator the machine will analyze the new cards, distribute the data thereon to the proper accumulators, and to a summary accumulator. The balance card is then 125 analyzed and the data thereon added to the summary accumulator.

Thus if a new card shows that the insured. 130

has died, one is subtracted from the number of policies in force, the amount of the policy is subtracted from the amount of insurance of that year, age and kind in force and the proper data will be delivered to the proper accumulator wheels for subsequent printing under the heading of "Died" on the report. Similarly, if a new card represents a revived or changed or discontinued policy it will be 10 added to or subtracted from the policies in force.

In actual practice, the cards representing new business or rather, changes, may be run through the machine first; followed in each 15 instance by the balance card of that group. The accumulators then will receive the data from the cards representing changes, and thereafter the balances will be run in to formulate the new balance.

20 There may also be instances where the card 10 represents a change in an existing policy without changing its kind. In such a case, when the card passes through the tabulator it is not desired to either add to or subtract 25 from the number of policies in force. There may also be cases where the change in the policy does not change the amount of insurance involved and wherefore it is not desired to either add to or subtract from the total 30 amount of insurance in force. To control the machine in such cases, the fields 19 and 20 may be used. The field 19 is of sufficient width to receive two digits and its corresponding field 19a contains two columns of hole 35 spaces. If a digit is printed to the left in field 19 corresponding perforations will appear in field 19a and the machine will be set up to perform an adding function, while if the digit is to the right the machine will be 40 set up to subtract. The number printed in this field also determines which of the accumulators other than that bearing the insurance in existence is to be affected. Thus, if as shown in Figs. 7 to 7b, the digit 1 is printed 45 to the left it will indicate that the amount of insurance on the card is to be added to the "Revival" accumulators as well as the "Existing" accumulators, i. e., the accumulators controlling the amounts printed in the re- 50 vival column in Fig. 5. If a 2 is printed to the left the amount is to be added to the "Existing" and "Credit" accumulators. A 1 to the right, however, indicates that the amount is to be subtracted from the "Existing" accumulators and added to the "Died" 55 accumulators. A 2 on the right causes subtraction from the "Existing" and addition to the "Discontinued" accumulators, while a 3 on the right causes subtraction from the "Existing" and addition to the "Debit" accumulators.

60 In field 20a, Fig. 2, following the table shown in Fig. 8, if there is a hole in the bottom one of the four hole spaces the machine 65 will suppress action of the counters showing

the number of policies in existence. The absence of a hole in such space will permit addition or subtraction in said counter according to whether the digit in field 19 is to the left or right. If there is a hole in the second space from the bottom, this will suppress action of the "Existing" accumulators which would otherwise take place under control of the holes in field 19a. The proper operation of the other accumulators, however, will take 70 place.

75 Referring now to the machine which is shown in perspective in Fig. 1, 21 represents the main supporting frame mounted on legs 22.

80 Generally, the machine is divided into a drive unit, a card feed unit, a perforation sensing unit, a translating unit, an accumulating unit, a printing unit, a finder unit and a plurality of control elements.

The drive unit

85 The drive comprises an electric motor 23 (Fig. 1) having a pulley 24 connected by a belt 25 to a pulley 26. The latter pulley is 90 fixed on a shaft 27 (Figs. 36, 44, and 37,) having a worm 28 meshing with a worm wheel 29 fixed on a sleeve 30 on shaft 30'. Loose on the sleeve is a gear 31 to which is fixed a disc 32 having a clutch latch 33 pressed by a 95 spring 34 toward engagement with the worm wheel 29. The wheel may have a groove 33' in its side to receive the latch so as to turn gear 31. An inclined member 35 is adapted to be moved into the path of the latch to lift the latter out of engagement with the worm wheel and to stop gear 31 when the tail 33' strikes the shoulder 35'. Adjacent the stop 35 and pivoted on the same shaft 50 therewith is a latch 51 (see also Fig. 44) pulled by a 100 spring 52 toward the disc 32. A pin 53 in the latch engages the back of the stop. When the stop is moved to inoperative position, it moves latch 51 out of engagement with disc 32, and when the stop 35 is moved to position to stop gear 31 it permits the latch 51 to move into engagement with disc 32. The parts are so positioned that when the tail 33' 105 strikes shoulder 35' the latch drops over the shoulder 54 on the disc 32 and prevents rebound of gear 31. Upon moving member 35 out of the path of the latch the latter will be pressed by its spring 34 against the worm wheel and will drop into the clutch groove as the latter is passing and cause the gear 31 to 110 rotate. Gear 31 actuates gears 36, 37, 38, 39. The gear 39 is connected through a universal joint 40 to a shaft 41 for controlling the return of the paper carriage as will hereinafter be shown.

115 Gears 36, 37 are loose on their shafts.

120 Loosely mounted on sleeve 30 is a gear 42 meshing with a gear 43 which in turn, meshes with a gear 44 fixed on a shaft 45 which carries a plurality of cams the functions of which 125

will be pointed out presently. Fixed to the gear 42 is a disc 46 carrying a clutch pawl 47 pressed by a spring 48 into engagement with a notched disc 49 fixed to gear 31. Thus, gear 42 will be actuated when gear 31 is turning if clutch 47 is in operative position. Also, when gear 31 is stopped, gear 42 will be stopped. The construction and operation of the clutch parts 47, 49 are similar to those 10 associated with gears 55, 56. These gears and disc 57 are on a sleeve 58 rotatable on the sleeve 30. Fixed on the sleeve 30 adjacent disc 57 is a notched disc 59 (see also Fig. 41). Carried on disc 57 is a clutch dog 60 actuated 15 by a spring 61 toward engagement with disc 59. Loosely mounted on shaft 50 is a stop 62 connected by a link 63 to a lever 64 on the control rod C-6. The stop 62 is adapted when moved to operative position to engage a projection 65 on disc 57 to stop the latter. A projection 66 on stop 62 is adapted to engage the tail 67 of the clutch dog to lift the latter out of engagement with disc 59 just before the parts are stopped. A latching pawl 68 25 on shaft 50 is pulled by a spring 69 into engagement with disc 57 and drops over the projection 65 as the latter strikes stop 62 and prevents rebounding. A pin 70 in latch 68 rests against the back of stop 62 so that when 30 the latter is moved to inoperative position the latch will be moved to such position also. The gear 55 actuates a gear 71 on shaft 72 and gear 56 actuates a chain of gears 73.

The clutch dog 47 and the rebound latch 35 68' for gear 42, as heretofore stated are similar to dog 60 and latch 68 and are operated in the same manner. The link 74 (Figs. 37 and 44) which actuates the clutch is connected as shown to control rod C-2. To this 40 rod is also connected a link 75, connected to a lever 76 on shaft 50. A pin 77 on gear 31 is adapted to engage the inclined end of this lever to cause rod C-2 to rock and thus unclutch gear 42 and stop the same. The purpose 45 of this will be seen later.

Adjacent to gear 42 on sleeve 30 is a member 78 (Figs. 36, 37 and 41) constrained to rotate with said sleeve by connection with a keyway 79, but free to move longitudinally 50 on the sleeve. Said member is provided with an inner circumferential cam groove 80 and an outer plain circumferential groove 81. An arm 82 fixed on gear 42 has a roller 82' reaching into the cam groove, while a lever 55 83 rotatable about a vertical axis on bracket 84 has a roller 83' engaging in the outer groove 81. Secured to lever 83 to turn about the same axis therewith is an arm 85 which is connected by a link 86 to a lever 87 secured 60 to and depending from control rod C-7. It will be seen that when gear 42 is clutched to rotate with sleeve 30 with which member 78 is always constrained to rotate, no relative movement will take place between roller 82' and groove 80. But when said gear is

locked against rotation, member 78 continuing to rotate, the cam groove working in conjunction with the now fixed roller 82' will cause member 78 to slide along the shaft sleeve 30. This, in turn will cause levers 83, 85 to turn about their common axis, moving link 86 longitudinally and rocking control rod C-7. This takes place in total-taking and will be dealt with in connection with that subject later.

70

75

The card feed

The cards 88 are stacked in a supply pocket 89 (Figs. 1, 10, 12 and 14) and pressed against the feed head 90 by a back 91 movable between the walls of the pocket and carrying a rotatable geared cylinder 92 reaching through the bottom of the back and meshing with a fixed rack 93. The cylinder contains a coil spring constraining it to rotate and thus press the cards forward. A latch 94 may be provided to engage the rear edge of the pocket to lock the back in such position while cards are being inserted.

100

105

110

115

120

125

130

The card picker 95 is secured to the head 90 which is slidably mounted on vertical guide posts 96. These posts are hollow and contain actuating rods 97 (see also Fig. 13) attached to the head 90 by screws 98 reaching through slots 99 in the posts. The slots are of sufficient length to permit the proper up and down movement of the head. The lower end of each of the rods 97 has fixed thereto an arm 100 (see Fig. 32) reaching out through a slot 101. This arm is connected by a link 102 to a lever 103 fixed on a shaft 104. Oscillation of said shaft will cause up and down reciprocation of the picker. The opposite end of shaft 104 has fixed thereto a pair of lever arms 105, (Figs. 12, 13, 30) having universal connection at 106 with a link 107. Said link has a slot 108 through which projects a pin 109 fixed to one arm 110 of a bell crank 111 loosely mounted on shaft 112. Shaft 112 has fixed thereon a crank arm 122 connected by a spring 123 to the bell crank 111. The pin 109 besides engaging in slot 108, engages one arm 124 of a bell crank 125 which is loosely mounted on shaft 112 and is connected by a spring 126 to the link 107. The arm 110 of bell crank 111 carries a second pin 127 engaging in a slot 128 in a lever 129 fixed to shaft 112. The shaft 112 is adapted to be oscillated by mechanism presently to be described. This oscillation is adapted to cause oscillation of the shaft 104 in the following manner:

Presuming shaft 112 to be turning counter-clockwise (as viewed in Fig. 30), spring 123 will cause bell crank 111 to follow and this in turn, will, through pin 109, when the latter reaches the upper end of slot 108, raise link 107 and turn shaft 104 counter-clockwise as viewed in Fig. 32. When the shaft 112 turns clockwise the link acting on pin 127 turns bell

5 crank 111 clockwise. This in turn, through pin 109, turns bell crank 125 clockwise, stretching spring 126 and pulling down upon link 107 to turn shaft 104 clockwise as viewed in Fig. 32. This driving connection between shafts 104 and 112 is resilient in both directions, so that shaft 104 can be locked against operation to suppress the feeding of cards, during a total operation, for instance; while 10 the other parts of the machine including shaft 112 continue to operate. In this connection it will be seen that if shaft 104 is locked and shaft 112 turns counter-clockwise, when pin 109 reaches the end of slot 108 and 15 link 107 will not be raised, spring 123 will simply stretch. And when shaft 112 turns clockwise and pin 109 turns bell crank 125, the spring 126 will stretch.

Oscillation of shaft 112 is effected in the 20 following manner:

The opposite end of the shaft, (Figs. 18 and 12) has fixed thereon a lever 113 connected by a link 114 to a bell crank 115 pivoted at 116 and carrying follower rollers 117 cooperating 25 with complementary cams 118 on shaft 119. This shaft has fixed thereon (see also Figs. 36 and 47) a gear 120 meshing with a gear 121 on the same shaft with gear 43. The rotation of shaft 119 thus causes oscillation of shaft 30 112.

Each downward stroke of the card picker feeds one card from the stack to the dotted line position 130 (Fig. 13) after which the clips 131 take it as shown in Fig. 32 and move 35 it to the position 132 when it is analyzed by the perforation sensing pins presently to be described. From the position 132 the cards are taken by another set of clips 133 and carried downwardly into the discharge stack 134.

The clips 131, 133 are carried by a frame 135 (Figs. 13 and 14) slidably mounted on the guide posts 96 as at 136. Said frame is connected by a link 137 to the lever 122 which, as we have seen is constantly oscillated by the shaft 112 (Fig. 30). Thus, the clips are moved up and down constantly while the machine is in operation.

Referring specifically to the upper set of clips, (Figs. 12 and 32) there is a back clip 131a loose on a shaft 138 and a front clip 131b fixed on said shaft. Rearwardly extending projections of said clips are interconnected by a spring 139 tending to close the clips. Fixed on the shaft 138 is a bell crank 140 connected by a link 149 to a lever 140a on the corresponding shaft 138a of the lower clips. The bell crank is also provided with a follower adapted to cooperate with a cam lever 141 pivoted at 142 to a fixed portion of the machine. Also pivoted to a fixed part of the machine is a latch member 143 connected to the cam 141 by a spring 144. The latch normally prevents the cam from turning counter-clockwise while the spring besides holding the latch in operative posi-

tion, tends to restore the cam to normal position. Presuming the clip carriage to be moving upwardly, the cam 141 will turn lever 140 and shaft 138 clockwise. The clip 131b which is fixed on the shaft will also turn 70 and, being connected by spring 139 to clip 131a, cause the latter to follow. The clip 131a is provided with a projection 145 adapted to engage a stop 146 on the carriage at the moment the clips reach the plane of the card. This happens just before the lever 140 reaches the end of the incline of cam 141. The clip 131a turns slightly farther as the lever reaches the end of said incline so that the clips will be open during the remainder of their upward stroke and ready to straddle the lower edge of the card. At the end of the stroke of the clip carriage a member 147 carried thereby will strike a projection 148 on latch 143, tilting the latter and releasing 85 the cam 141. The cam will now turn counter-clockwise under the pressure of lever 140 which is actuated by a spring 150 pulling downwardly on link 149. The lever 140 is thus permitted to turn counter-clockwise and close clip 131b upon the card. Pivotally mounted on the clip carriage is a latch 151 to which the spring 150 is also connected, tending to turn the latch into locked engagement with member 140a. When the clips are 90 released by cam 141 to grip a card, the shoulder 152 on member 140a engages a corresponding shoulder on the latch and holds the clips in proper position, i. e., the clip 131b being fixed on shaft 138 is held rigidly in the plane of the card, while the clip 131a is pressed by spring 139 against the back of the card. With the parts in such position the clip carriage moves downwardly carrying 95 the card to the position 132. When the card reaches this position, its lower edge strikes the stops 153 (Figs. 13, 14, 31). These stops are pivotally attached at 154 to a bracket 155 on the back of the plate 156 and are adapted to reach through suitable slots in the plate 100 into the path of the card, but are normally held out of such position by springs 157. Slidably mounted in guides 158 on the back of plate 156 is a strip 159 having a cam section 160 adapted to engage rollers on the rear ends of the stops. The clip carriage has a stud 161 adapted to engage a stud 162 on strip 159 near the end of the downward stroke of the carriage, so that after the previous card has cleared the sensing position 105 110 and just before the new card arrives the cams 160 will force the stops into operative position. Near the end of the upward stroke of the clip carriage, the stud 161 engages a second stud 163 on strip 159 and raises the cams 160, permitting the stops 153 to move to inoperative position.

The lower set of clips 133 are similar to the upper set, and being connected thereto by link 149, operate in the same manner and at 115 120 125 130

the same time. Thus, while the upper clips are taking a card from the dotted position 130 and moving it to position 132, the lower clips are taking a card from position 132 and 5 moving it to the discharge stack 134.

After the cards are stripped from the clips by the stops 153 and the bottom 164 of the discharge pocket, and the clips are clear of the lower edges of the cards, the latch 151 strikes a post 165, shown in Fig. 12 as having a set screw in its top for fine adjustment. This tilts the latch 151 and releases the member 140a. The spring 150 on link 149 then turns shafts 138, 138a counter-clockwise until the outer shoulder 152a on member 140a is caught by the latch. The turning of said shafts turns the clips to the position of Figs. 12 and 14; back of the plane of the cards. The clips are then ready to be 15 moved upwardly back of the cards which then have deposited until actuated near the upper end of the stroke as set forth.

If the machine is set to detect a change in group designation of the cards and to take a 25 total of data on the previous group when such change takes place, the card feeding operation is suspended while the machine passes through the total-taking operations. The mechanism for effecting this suspension includes a link 166 connected through lever 167 to a shaft 168 to rock the latter. Said shaft has at its opposite ends levers 169 carrying upwardly extending links 170 having pin and slot connection with the latch members 143. 30 An upward thrust of link 166 to the dotted line position 166a (Fig. 32) will cause a downward pull of links 170, turning latches 143 to inoperative position, so that when member 140 engages cam 141 the latter will turn counter-clockwise and permit the clips to remain in the rear of the plane of the cards instead of causing them to grip a card. Shaft 168 also has a latch 171 adapted to cooperate with a crank 172 fixed on shaft 104 in the manner indicated 35 in dotted lines to prevent oscillation of shaft 104, and in this way prevent the operation of the card picker 95. The latch 171 is loose on its shaft, and has a spring attached to its rear end tending to pull it into locking position. 40 A crank 174 fixed on the shaft 168 has a pin engaging the rear end of latch 171 holding it normally in unlocked position. When the shaft rocks the latch is permitted to operate. The shaft 168 also has a lever 175 connected 45 through a link 176 to a lever 177 pivoted at 178 and connected at its other end to a frame 179. The rocking of the shaft thrusts the frame between plate 156 and the stops 153 as 50 shown in Figs. 30 and 31 to hold them in operative position while the cams 160 continue to move up and down.

Perforation sensing unit

65 When the card is in the position 132 of Fig.

13, it rests between the plates 156 and 156a. (See also Fig. 14.) These plates are provided with holes 180 arranged to conform to the hole spaces on the card, and when the card is in position the hole spaces register with these holes. Associated with the holes are the feeler pins 181. The forward ends of the pins rest normally in the holes in plate 156 and are thus supported and guided thereby. The rear ends of the pins receive similar support by a plate 182 (Fig. 12), while a diagonal frame 183 (Figs. 10 and 12) near the middle of the pins may be provided for intermediate support. The pins are urged forward by individual helical compression springs 184 mounted on the pins and acting between a fixed frame 185 and a collar 186 fixed on each pin, (see also Fig. 14). Another collar 187 on each pin is adapted to cooperate with the frame 185 to limit the forward movement of 80 the pins. Another collar 188 also fixed on the pin cooperates with a slotted plate 189 for normally holding the pins in their backward or non-reading position. This plate is fixed on a frame 190 adapted to rock on a fixed axis 90 191. A bell crank 192 pivoted at 193 has a pin and slot connection with the frame 190 and is connected by a link 194 (Fig. 30) to a crank 195 fixed on a shaft 196. The outer end of this crank has a tension spring 197 connected at 198 to the bed of the machine. The other end of shaft 196 has a lever 199 provided with a cam follower acting on a cam 200 on shaft 112. Spring 197 tends to hold the follower against cam 200 so that the oscillation of shaft 112 causes shaft 196 to oscillate also. The link 194 thus rocks bell crank 192 to move the plate 189 alternately forward and backward, to release the pins and to then restore those that may have advanced. A cam lever 201 (Fig. 12) may be provided to rock a lever 202 to lift the outer end of bell crank 192 to manually withdraw the pins 181. A spring 201a will restore the cam lever 201 and lever 202 when released. The shaft 196 has fixed thereon a lever 203 (Figs. 13 and 30) adapted to be locked against downward movement by a latch 204 pivoted at 205 and connected by a crank 206 having pin and slot connection with link 207 to a rock lever 208 having pin and slot connection with the strip or slide 159. The up and down movement of said slide then causes the latch to oscillate on its pivot, moving to and from locking position with respect to lever 203. As shaft 112 rocks clockwise and lever 199 rides into the depression of the cam 200 the pins are released to take a reading of the card. When lever 199 rides to the higher part of the cam 115 as in Fig. 30, the pins are restored. The cam will now rock counter-clockwise to its starting position while the cars are being shifted. In order that the pins shall not advance during 120 this period the latch 204 will prevent lever 199 125 130

from following the cam on the return stroke. Ordinarily, the pressure of springs 184 and spring 197 tending to turn lever 203 downwardly, will frictionally hold latch 204 in place until it is positively removed. Means may be provided for holding the parts positively in locked position, however. This is shown as comprising a lever 209 fixed on the pivotal shaft 205. When the parts are moved 10 from the positions shown in Fig. 13 to those shown in Fig. 30, a member 210 on lever 208 will lock lever 209 down. Toward the end of the stroke, when the slide 159 moves downwardly, member 210 releases lever 209, and 15 thereafter, link 207 will move latch 204 to inoperative position. At this time, the lever 199 will be on the opposite high portion of cam 200 and the pins cannot advance.

Near their rear ends, the pins have fixed 20 thereon, collars 211 (Figs. 12 and 56). Certain groups of these collars are adapted to be engaged by bell cranks 212, pivoted at 213 and connected by links 214 to actuating levers 215. Others of the collars are adapted to be 25 engaged by stop members 216 slidably carried in frame 217 and having pin and slot connection with others of the actuating levers 215. When any of these levers are thrust forward the respective stops 212 or 216 will 30 engage corresponding collars 211 and prevent those pins from advancing when all of the pins are released to take a reading. In order to hold the parts positively in the positions to which they are moved, and especially 35 against the action of the pin-actuating springs 184 when the pins are locked against operation, the fixed plate 218 (Fig. 11) having slots 219 in which levers 215 are guided, are provided with shoulders 220 behind 40 which the levers are adapted to spring.

Referring again to the card shown in Figs. 2 and 3, it will be remembered that there are two rows of printed data on the upper half of the card, and two corresponding rows or 45 fields 11a and 12a; each field comprising vertical columns of four hole spaces each. It will now be seen that the pins 181 are arranged in columns of eight pins each; the four upper ones being adapted to cooperate 50 with the upper field 11a and the four lower ones to cooperate with the lower field 12a.

An additional pin 221 (Figs. 12, 13 and 14) is shown below the other pins and operates 55 through holes 222 in plates 156, 156a. This pin ascertains the presence or absence of a card in the sensing position. There is no hole space in the card corresponding to this pin, so that if there is a card present when all of 60 the pins are released to take a reading the pin 221 will be prevented by the card from advancing, while if there is no card present the pin will advance. This pin in turn controls mechanism which will be described 65 later.

The translating mechanism

When one or more of the pins of the groups of four advance through holes in the card, the reading must be translated from the combination code to its definite numerical value for transmission to the printing and accumulating elements. The mechanism for performing this function will now be described.

Integral with each of the pins 181 is a 70 block 223 (Figs. 10, 12, 27, 28 and 29). Each block has a slot 224 into which a projection 225 on a lever 226 reaches. Taking one column of four of the lower set of pins, it will be seen that the two lower pins 181 are thus 75 connected with one lever 226 and the two upper pins of the set with a second lever 226a. These levers are fixed on rods 227, 227a, supported by members 228 in which they are 80 adapted to rock. On the other ends of these 85 rods are fixed stepped stop members 229, 229a. Fig. 27 shows the stops in their normal positions; held so by springs 230. As shown in Fig. 15, these springs are connected to the stops at a point sufficiently high to have the 90 proper actuating effect, and may be anchored to another of the stops close to its axis so as to produce no appreciable actuating effect. Those of the springs that have no stops ahead of them to which they can be anchored, may 95 be anchored to a fixed member 231, Fig. 27, in the machine.

The stepped stops 229, 229a cooperate with 100 depending projections 232, 232a, on combination combs 233, 233a. These combs are normally held up by a bar 234, Fig. 24, and are 105 adapted to be pulled downwardly by springs 235 when released by the bar 234.

The parts are shown in normal positions 110 in Fig. 27. It will be seen that the collars 187 on the several pins are staggered with respect to each other. Thus, when the pins are released by member 189 to be thrust forward by springs 184 (Fig. 14), the bottom pin, for instance, may advance a greater distance than the one immediately above it before the collars 187 engage stop 185. In other words, we will say that the second pin can advance one step and the bottom pin which is adapted to advance the substantially three times as far can advance three steps. If only the bottom pin advances, its block 223 will engage a shoulder 236 on the block of the second pin and it will thus be stopped when it has moved but two of its steps. When only the second pin moves it turns lever 226 and through shaft 227, turns stop 229 one step, so that when comb 233 is released it will descend one step. If only the lower pin advances it will set stop 229 to permit comb 233 to descend 115 two steps; while if both pins advance the comb will descend three steps. The third and fourth pins of the set operate in the same manner to control the setting up of the comparison comb 233a, and the several sets 120 125 130

- of four pins each in both the upper and lower rows operate similarly. Thus, if the combination of perforations being read represents "6", being in the top and bottom hole spaces 5 according to Fig. 4, the top pin will advance one step as in Fig. 28 and the bottom pin will advance two steps, setting the stepped stops so that the combs 233, 233a will descend two steps and one step respectively. Fig. 29 10 shows the positions of the parts where the two lower pins have advanced, taking a reading of "7". The comb 233 had descended three steps, while comb 233a has not descended at all.
- 15 In the timing of the machine the sensing pins are withdrawn while the combs are still resting on the stops 229, so that the stops cannot be restored at this time but must remain until the combs have been raised. The length 20 of the slot 224 in which the projection 225 operates will thus permit the pins to be restored, leaving the stops in operative position to be restored by their springs when released by the combs.
- 25 The restoring bar 234 for the combination combs as viewed from the right and left hand sides of the machine in Figs. 17 and 18 respectively, is movable up and down in guide slots 237 in the frame member 238 of the machine. Depending from each end of the bar 30 is a link 239 pivotally attached to levers 240 fixed on a shaft 241. One end of this shaft has a cam follower lever 242 (see Figs. 42 and 11) cooperating with a cam 243 on shaft 35 45 (see also Fig. 36). A spring 244 (Fig. 18) fastened to the frame 238 and to a lever 245 on shaft 241 tends to rotate shaft 241 to resiliently hold the follower 242 on the cam. The oscillation of the shaft 241 by the spring 40 and cam will cause the bar 234 to be lowered and raised once each card cycle at the proper time to permit the combs to take the reading of the stepped stops 229.
- Should there, for any reason, be no card at 45 the sensing station when the pins take their reading, provision is made to suppress the lowering of the bar 234 which would be followed by the dropping of all of the combs to their lowest step. The mechanism for effecting 50 this suppression is as follows: A rod or shaft 246 (Figs. 17 and 18) carries at each end, a latch 247. When said rod is turned clockwise as seen in Fig. 18 (counter-clockwise as seen in Fig. 17) the shoulders on the 55 upper ends of these levers will be positioned under the bar 234 when the latter is in its upper position. As the cam 243 rotates now the spring 244 will be prevented from causing follower 242 to follow. A link 248, Fig. 17, connected to one of the latches 247, has at its 60 other end a slot 248a, Fig. 13, through which a stud 249 on a lever 250 projects. The lever 250 is fixed on the shaft 196 which, as we 65 have seen, oscillates while the machine is operating, and carries a pair of shear-like ele- 70 ments 251 urged toward closed position by a spring 252. Between the outer arms of the shears is a pin 253 fixed on the link 248. As the lever 250 oscillates, the stud 249 rides idly in the slot 248a, acting as a support for the end of the link 248, while first one and then the other of the shear blades engages pin 253. When one blade engages pin 253, the other will engage stud 249 and the link 248 will be moved laterally unless it is locked against 75 such movement, in which case the spring 252 will stretch and the shear blades will open. As seen in Fig. 17, when link 248 is moved to the left it will place the latches 247 under the bar 234 and lock the latter in the upper or restored position. Fig. 18, however, 80 shows a lever 254 engaging a projection on latch 247, preventing the latter from moving to locking position. The card-sensing pin 221 heretofore referred to (Fig. 12) is adapted 85 to rock a lever 255 fixed on a rod 256. The other end of this rod (Fig. 15) has fixed thereon a lever 257 attached to a link 258 having pin and slot connection with the lever 254; a spring 259 being connected to the link 258 90 and to the pin which is fixed in the lever 254. Whenever the feeler pins are released to take a reading, if a card is present at the sensing station the pin 221 will be prevented from advancing. But when no card is present the 95 pin will advance, rocking lever 255 and rod 256; raising link 258 and lever 254. This releases the latches 247 so that they are now free to turn clockwise as viewed in Fig. 18. While this is taking place the link 248 (Figs. 100 13 and 17) is being urged to the left by its connection with lever 250, and the latches are thus moved to locking position to prevent the lowering of the bar 234 and the several combination combs 233. When the feeler pin 221 is retracted the link 258 (Figs. 15 and 18) will be lowered and the spring 259 will stretch, leaving the lever in the upper position on the latch 247. The pressure of the bar 234 upon the latches 247 will prevent them from being 105 moved by the shear elements 251 (Fig. 13) at the time that the feeler pins are retracted. But, when at the proper time the parts perform their normal restoration functions, the bar 234 will be slightly raised, and, the latches 110 being thus released, will be moved to normal position and the spring 259 will restore lever 254 to the position shown in Fig. 18 to lock the latches out.
- Turning now to the construction and function of the combination combs, the combs are mounted for movement up and down in frame 260 (Fig. 24) and are provided with notches 261 of varying depths. Adjacent to each pair of combs 233, 233a is a set of feeler bars 262, 115 slidably mounted in frame members 263. Each feeler bar has a lateral projection 264 extending across the notched edge of the two combs, (see also Figs. 27 and 28). Associated with the feeler bars are the restoring 120 125 130

members 265 engaging in notches 266 in the feeler bars. The parts are shown in normal or restored position in Fig. 27, while in Fig. 28 the restoring members are shown moved to the right, releasing the feeler bars so that they are free to be moved to the right by springs 267 connected to the bars and to the restoring members. The restoring members are operated in the following manner: The several members 265 are all connected at their opposite ends to yokes 268 (Fig. 17); being held in place by strips 269. The yokes are slideable in guides 270, and are connected at 271 to toggle 272, the other side of which is connected to a fixed frame piece 273 and the middle of which is connected to depending links 274 (see also Fig. 18), which are, in turn, connected by pin and open slot to the arched levers 275; springs 277 acting to hold the links 274 in hooked engagement with the pin on the levers. The levers 275 are fixed on a shaft 276, which also has a pair of cam follower levers 278, 279 (Figs. 11 and 62) cooperating with complementary cams 280, 281 (see also Fig. 36). After the combs have taken their reading positions, the cams 280, 281 rock shaft 276 raising link 274 and breaking the toggle 272, so that the yokes 268 with the restoring members 265 will move to the right (see Fig. 17). Springs 282 may be provided to aid in the movement of the yokes against the action of the springs 267 (Fig. 27). After the feeler bars have advanced and performed their functions, the cams depress the toggle again and restore the bars.

During total-taking operation, it is desired to suppress the operation of the feeler bars. For this purpose a lever 283, Fig. 17, may be fixedly connected to the toggle 272. A stud 284 on said lever is adapted to be engaged by a latch 285 fixed on a rod 286, on which is also fixed a lever 287 connected by a link 288 to a lever 289 having a cam follower 290 cooperating with a cam 291. When the cam operates during total-taking in a manner to be presently disclosed, tilting lever 289 clockwise, the rod 286 will also rock clockwise and latch 285 will engage stud 284 to prevent the toggle 272 from breaking. At the same time, a cam 292 also fixed on rod 286, acting upon a stud 293 on the link 274 will disconnect said link from lever 275 so that the latter may rock freely.

Referring now to Figs. 24, 27 and 28, after the combs have taken their reading positions, and the feeler bars have been released, the springs 267 will tend to advance the bars to the right. The bars will either be stopped by the edge of the combs, or advance a distance dependent upon the combination of notches presented to the projections 264. Figs. 81 to 81c represent diagrammatically the operation of the parts. In these views the combs are shown in tandem arrangement instead of side by side, and the projection 264 is shown in

two parts. Fig. 81 shows the combs in normal positions with comb 233 blocking the passage of projection 264, so that the feeler bar cannot advance. Fig. 81a shows comb 233 as having descended two steps so that each comb now presents a deep notch to projection 264 and the feeler bar has advanced three steps. In Fig. 81b both combs have descended two steps, the comb 233 presenting a deep notch and 233a an intermediate notch, so that the bar has advanced two steps, while in Fig. 81c comb 233 has descended two steps, presenting a deep notch and comb 233a has descended one step, presenting a shallow notch and the bar had advanced but one step. 80

The printing unit

Adjacent to the ends of the feeler bars are the type carrier bars 294, Fig. 24, adapted to move up and down in frame members 304. A spring 295 attached to a bracket 296 on the type bar (see also Fig. 88) and to a cross member 297 serves to raise the type bar when the latter is released by the restoring bar 298. The upper end of the type bar carries the type elements 299 which by the raising of the type bar, may be selectively brought to printing position, in alignment with the plunger 300 which, in turn, when struck by the hammer, 301, impels the type against 90 the platen 302, or a sheet of paper thereon. The edge of the type bar toward the feeler bars has integrally fixed thereto, a three-step bracket 303 which, when the type bar rises is adapted to engage on one of its steps, the 100 feeler bar 262 which may have advanced. The feeler bar will thus stop the type bar. The position in which the type bar is stopped and consequently, which of the type elements is placed in printing position is dependent upon which of the feeler bars had advanced and the number of steps of such advance. Thus, the combination of holes in the four hole spaces will, by the resultant setting of the feeler pins 181, stepped stops 229, 229a, 110 combination combs 233, 233a, feeler bars 262 and type bar 294, cause the proper type element 299 to be placed in printing position. In Fig. 81a, where the feeler bar had advanced three steps it has caught the top step of bracket 303. In Fig. 81b the feeler bar has advanced two steps and caught the second step of bracket 303. In Fig. 81c the feeler bar has advanced but one step and caught the third step of the type bar bracket. 120 In Fig. 81 where the feeler bar has not advanced at all the steps 303 are free to pass this particular bar until stopped by another. Thus, in Fig. 28, of the five feeler bars illustrated, the fourth from the bottom has advanced one step and the type bar bracket has risen past the three lower feeler bars and been stopped by engagement of its lower step with said fourth feeler bar. 125

The manner in which the type elements 299 are carried by the type bar, resiliently held in normal position and returned thereto after being actuated for printing, is more specifically shown in my United States Patent No. 1,260,705 for recording mechanism, dated March 26, 1918.

The bar 298 (Figs. 17, 18 and 24) which restores the type carrier 294 is slidably mounted in slots 305 in members 306 at its opposite ends. Links 307 connected to the ends of the bar are in turn connected to levers 308, 309 on the left and right sides of the machine. Said levers are fixed on a shaft 310 which, in turn has fixed thereon a bell crank or double cam follower lever 311 (Figs. 11 and 42) cooperating with complementary cams 312, 313 on the main cam shaft 45 (see also Fig. 36). The timing of the cams is such that the type bars are released immediately after the feeler bars have advanced, and restores immediately after the printing operation. The member 297 to which the springs 295 which raise the type bars are attached is connected by upright pieces 314 (Figs. 24 and 52) to the restoring member 298, and is slideable up and down in guides 315. With this construction it is not necessary to have such long and strongly tensioned springs as would otherwise be necessary, as the upper anchorage of the springs is raised with the rising of the type bars.

The rear edge of each type bar is notched as shown at 316 (Fig. 24), and a pawl 317 is provided to cooperate with each bar. A plate 318 reaches across all of the pawls (see also Fig. 52) to normally hold them all disengaged from the type bars, while a spring 319 connected to the plate and to each pawl tends to turn the plate about its axis 320 and the pawls into the notches 316. Viewing the parts in Fig. 18 from the opposite end to that shown in Fig. 24, the rod 320 is provided with an actuating lever 321 having pin and slot connection with a link 322; the slot being in the link and being L shaped as shown. A spring 323 normally holds the link 322 to the left with the pin in the narrow part of the slot. The lower end of link 322 is connected to a lever 324 fixed on a sleeve 325 loosely carried on a shaft 326 (see also Fig. 11). Fixed on the sleeve 325 is a cam follower lever 327 cooperating with a cam 328. Said cam rocks the sleeve clockwise as viewed in Fig. 18, and pulls down on link 322 against the action of spring 329 to remove the pawls from engagement with the type bar. After the several type bars have been set by the feeler bars 262 (Fig. 24) ready for the printing operation, the cam releases the parts, permitting the spring 329 to raise link 322. The plate 318 then releases the pawls 317 to enter notches 316 before the feeler bars 262 are restored. Thus, the restoration of the feeler bars does not

70 permit the type bars to be thrown upwardly by their springs 295 to meet the descending restoring member 298. The pawls will hold the type bars in their set positions until the member 298 engages them on its downward stroke.

75 During the operation of the machine there may be instances when the operator has to remove a card from the sensing position, as, for instance, when a wrong or misplaced card is fed to the machine and causes automatic stoppage thereof. To remove the card the operator turns lever 201 (Fig. 12) clockwise to withdraw the pins from the card. He then removes the card from the machine and releases said lever, whereupon the sensing pins 181 all advance and transmit false readings to the translating elements. When the machine is restarted it completes the unfinished cycle before it commences operation upon the next card. In order to suppress the false reading so that it will not be recorded during this completion of the cycle, I have shown means for causing the pawls 317 to prevent the type bars from rising when released. To this end I have connected the link 322 (Fig. 18) to the lever 201 (Fig. 12) by means of a link 330 connected to link 322 and to a bell crank 331 (Fig. 11) pivoted at 332; the bell crank being in turn connected by a link 333 to a lever 334 fixed on the same shaft as lever 202. When the cam lever 201 is actuated to restore the sensing pins 181 before removing the card, the link 333 will be moved to the left. This will turn link 322 to the 100 right so that the wide part of the slot therein will register with the pin on lever 321. The link will be locked in this position by a latch 335. When this takes place the pawls will not yet have been withdrawn from the type bars after their last operation, so that when the cam now pulls down on link 322 to normally effect such withdrawal, the play of the pin in the slot prevents actuation of lever 321. However, this downward stroke of link 322 105 releases it from the latch 335 which, by reason of a stop 336, cannot follow. The link will then move slightly to the left under the strain of spring 323 but will be stopped by engagement of the shoulder in the slot with the pin on the lever 321 as will readily be seen. The movement to the left is sufficient to prevent retatching of the link when it is again raised. Thus, the pawls 317 are in engagement with the type bars when the bar 298 releases them to record the false reading. The pawls will then prevent the type bars from rising and in this way prevent recording during the cycle in question. When, at the usual time 115 the cam releases the link 322 to permit the pawls to enter, they will already be in engagement with the type bars. The rising of the link then, will present the narrow part of the slot to the pin in lever 321 and spring 120 125 130

323 will pull the link to the left to the position of Fig. 18.

The hammer action

5 The hammers 301 (Fig. 24) are loosely supported on a shaft 338 and are adapted to be impelled by individual springs 339 into contact with the plungers 300. A latch 340 cooperates with the tail of each hammer to normally hold it inoperative. A spring 341 holds the latch resiliently in such position. An actuating member 342 is loosely supported on a rod 343 carried by depending levers 344 fixed on a shaft 345. Clockwise rotation of shaft 345 will pull member 342 to the left. Said member is held in its upward position as shown by a spring 346 and is adapted to be depressed by a lever 347 pivoted at 348. A shoulder on the type bar 294 depresses the rear end of lever 347 against the action of a spring 349, when the type bar is in restored position. When the type bar rises to a printing position, it releases lever 347, which, being actuated by spring 349, engages and depresses member 342. Said member then latches over a lateral projection 350 on the latch 340, so that when member 342 is moved to the left it will move the latch and release the hammer. This releasing takes place after the type bars have all been set for printing. For this purpose, the shaft 345 has fixed thereon a lever 351 (Fig. 18), connected by a link 352 to a lever 353 fixed on a shaft 354. This shaft, as shown in Figs. 42 and 62, has fixed thereon, a cam follower lever 355 cooperating with a cam 356 on the cam shaft 45. When the shaft 345 is rocked the hammers corresponding with type bars that have been raised will be released while all others of the hammers will remain locked. After the hammers have performed their function, they will be restored by a bail 357 fixed on the shaft 338, on which is fixed a lever 358 (Fig. 18), connected by a link 359 to a lever 360 (see also Fig. 11), fixed on a sleeve 361 loose upon the shaft 276 (see also Fig. 42). Fixed on sleeve 361 is a cam follower lever 362 cooperating with cam 363. The link 359 is pulled upwardly by a spring 364. The cam turns shaft 338 clockwise as viewed in Fig. 18 or counter-clockwise as viewed in Fig. 24 to restore the hammers, while the spring turns the bail 357 to the position shown in Fig. 24 when released by the cam.

The lever 347 is adapted to actuate member 342 only when the type bar has risen to present a significant figure on the printing line.

The latch 340 has an oblique lateral projection 340A which extends behind the next adjoining latch on its right as shown in Fig. 15. Thus if any one of the latches 340 is rocked by member 342 it will cause a similar action in the latch to the right and this will be transmitted laterally to the first latch having no projection (as at 341b in Fig. 15).

This will cause the printing of zeros in columns having no significant figures between the column having the first real number and the end of that group.

70

The paper carriage

The paper carriage 365 (Fig. 24) is mounted for lateral movement with respect to the machine on bearings 366; the fixed bearing race member 367 being an integral part of the machine frame. Loose on a rod 368 as an axis are a pair of oppositely disposed brackets 369. Between these brackets and rotatably supported thereby are two platens 302 and 302—A having the usual manual actuating knobs 370, 371 (Fig. 23). The rearward extension of each bracket 369 may be connected by springs 372 (Fig. 17), to the carriage frame to tend to neutralize the weight of the platens on the brackets so that the latter may more readily be turned upon their axis 368. A link 373 is connected to each of brackets 369 and to levers 374 fixed on a shaft 375. Turning of the shaft will thus turn brackets 369 about their axis to raise or lower the platens so that either one may be placed in printing position. In Figs. 17 and 24 the upper platen is shown in printing position, while in Fig. 26 the lower one is shown in such position. To rock shaft 375 to change the positions of the platens, a lever 376 is fixed on said shaft. A slotted link 377 straddles a shaft 378 (Figs. 23 and 24) and is provided with a pair of cam followers 379 cooperating with complementary cams 380 fixed on the shaft 378. Turning of this shaft ninety degrees will shift the platens. Fixed on one end of shaft 378 is a ratchet 381 (Figs. 17, 23, 25 and 26). Loose on the shaft are a pair of levers 382, 383 having spring pressed pawls 384, 385 adapted to cooperate with the ratchet 381. Links 386 connect the levers 382, 383 to one arm of the bell crank 309 which, as we have seen, is fixed on shaft 310 and oscillates during the operation of the machine. The levers 382, 383 will thus oscillate on their axis so that one of the pawls will actuate the ratchet while moving in one direction and the other pawl will actuate it while moving in the other direction; both serving to turn shaft 378 clockwise and each turning it forty-five degrees. A complete back and forth oscillation of shaft 310 will then complete the shifting of the platens. As the shaft 310 and pawls 384, 385 are constantly operating and the shifting of the platens is to be effected only in accordance with the nature of the report being formulated by the machine, means may be provided for controlling the operation of the pawls upon the ratchet 381. To this end a double cam member (386—A) loose on shaft 378 is adapted; when in the position of Fig. 25, to prevent the pawls dropping into op-

130

erative contact with the ratchet prior to their active strokes. The cam 386 is connected by a link 387 to a lever 388 fixed on a shaft 389. Depression of lever 388 will turn cam 386 counterclockwise out of the way of the pawls so that the latter may turn the ratchet. To depress said lever, the shaft 389 is shown in Fig. 21 as having a cam follower lever 390 cooperating with a cam disc 391 loose on a shaft 392 but fixed with other discs to gear 392—A (Fig. 20). During listing and accumulating operations by the machine, the gear 392—A is idle and follower 390 is on a low portion of the cam, being held there by a spring 393 (see also Fig. 52). This prevents the pawls 384, 385 from shifting the platens.

After a series of listing operations, the total taking operations are introduced. This 20 includes the turning of gear 392—A and the consequent shifting of the platens. The manner in which the turning of gear 392—A is brought about will be explained in connection with the finder which institutes the total 25 taking operations.

When either of the platens is in printing position, the brackets 369 may be rigidly locked in position. For this purpose notched plates 394 (Fig. 24) are fixed to said brackets. 30 A lever 395 on the platen carriage has a lateral projection 396, shown as lodged in the lower of the two notches in the plate. The lever 395 has an oppositely reaching arm 396—A. The two arms carry followers 397, 398 engaging the opposite edges of the link 373. The connection between the link 373 and bracket 369 is by means of a pin in the bracket and a diagonal slot 399 in the link. As will be seen in Fig. 26, to reverse the positions of 40 the platens the link 373 must be raised. The connecting pin is at the left end of the diagonal slot 399. By reason of the locked condition of the platen brackets, the link will be cammed over to the left, moving with it the 45 follower 398 to turn lever 395 clockwise. This will remove the projection 396 from the upper notch, in this instance, in plate 394, releasing the brackets 369 so that the continued stroke of link 373 will move the platens to 50 the position of Fig. 24. At the end of this stroke the follower 398 will drop into a notch 400 in link 373 under tension of spring 401 (Fig. 18) and relatch the platens in this position. A downward pull of link 373 now will 55 cause the link to be cammed over to the right as will be understood by reference to Fig. 17. This will actuate follower 397, turning lever 395 to unlatch the platen brackets again so that the shifting of the platens in the other 60 direction may be effected by the continued downward pull of link 373. As said link descends the follower 397 will bear against the slanting edge of the link and release the 65 projection 396 to drop into the upper notch 70 in plate 394.

The shaft 378 may be provided with a notched wheel 402 (Figs. 23 and 52) fixed thereon. A spring-pressed lever 403 having a roller 404 pressing into the notches will serve to hold the shaft in the position to which it 70 is turned. A knob 402—A having bevel gear connection with shaft 378 may be provided for, manually shifting the platens.

The rotation of the platens to feed the paper is effected as follows: Fixed to one 75 end of rod 368 (Figs. 17 and 26) is a lever 405 carrying a pawl 406 urged by a spring toward engagement with the feed ratchet 407 of the platen which is in printing position. A link 408 connected to the pawl 406 has slot 80 connection with a stud 409 fixed to the bracket 369. A pin 410 on the link 408 cooperates with a cam 411 loose on the stud 409. The length of the link 408 from stud 409 to the pawl determines the depth of grip 85 that the pawl will take on the ratchet 407 when actuated. By turning the cam 411 from the position against stop 412 in Fig. 17 to a position against stop 413 the effective length of the link 408 is changed (see also Fig. 26a). 90 The cam 411 may be locked in its set position by any suitable detent arrangement cooperating with notches in the sector plate 414. This plate is loose on the stud 409 and is connected by a link 415 to bracket 369 which normally 95 prevents it from turning on stud 409. The actuation of the pawl to turn the platen is effected by rocking of shaft 368. For this purpose said shaft has a lever 416 (Fig. 24) fixed thereon. The lower end of said lever is provided with a flanged roller 417 cooperating with a bifurcated lever 418 fixed on a shaft 419. This shaft also has fixed thereon a cam lever 420 (Fig. 17). A link 421 attached to lever 416 has pin and slot connection with a member 422. As lever 416 is constantly rocking, the link 421 will be reciprocated up and down. A stud 423 on the link will thus engage the cam edge of lever 420 and rock shaft 419. This motion will then be transmitted through levers 418 and 416 to shaft 368, rocking lever 405 so that pawl 406 will grip and actuate the ratchet 407. With the parts in the position of Fig. 17 the platen will be turned one line space. Should the 100 platens then be shifted to present the lower platen for the printing of a total, the movement of bracket 369 will through link 415, turn the sector plate 414 on its axis. This will turn the cam member 411 with respect to pin 410 and increase the effective length of link 408, so that although the parts are set for single space feed of the upper platen, a double space feed of the lower platen will be 105 effected when that platen is moved to printing position. However, should cam 411 be turned to the stop 413 to effect double space feed of the upper platen, shifting of the platens does not alter the feed of the lower platen as turning of the cam 411 beyond a given point 110

does not alter the effective length of link 408.

Loosely carried on the other end of shaft 368 (Fig. 18—A) are a pair of levers 424 having roller detents spring-pressed into engagement with notched wheels 425 on the platen shafts to resiliently centralize the platens and to hold them where set.

A system of levers 426 may be provided for easing the pressure of the clamping rollers 427 against the platens in a manner well known to facilitate the insertion of the paper.

There are instances when it is desired to suppress the paper feed, as for instance, during accumulating or other non-printing cycles of the machine. To effect this, the link 421 may be inclined so that the stud 423 will not actuate the cam 420. Thus, when shaft 378 (Figs. 23 and 25) is being turned to shift the platens, a notched wheel 428 fixed on said shaft will actuate a lever 429, pulling down the links 430, 431 and turning the guide member 422 about its axis. This shifts the stud 423 to the left of the cam lever 420 so that the stud will miss the cam on its upward stroke which takes place during the shifting of the platens. At the completion of the shifting of the platens the notched wheel 428 releases the lever 429 and the parts resume their normal positions under the influence

of spring 432. Another instance is in connection which the printing of the report of Fig. 5. Several machine cycles are required to print each line of data contained on this sheet. After one printing operation the carriage is moved laterally to place other columns in position to receive impressions from the type. While listing operations and part of the printing of the summary sheet are taking place, the carriage is in such position

that a cam 435 (Figs. 17 and 23) fixed to the carriage will maintain a lever 436 depressed. A shoulder 437 (see also Fig. 25) on said lever rests on a stud 438 in member 422; the lever and stud being connected together by a spring 439. When the lever is depressed as in Fig. 17, member 422 may be in normal position, but when the paper carriage moves to the left as in Fig. 23, the lever 436 is released. Its spring 440 then turns it counterclockwise, actuating members 422, 421 to the position of Fig. 25. The paper feed will thus be suspended until the carriage is returned to normal position.

Another instance where the paper feed is suppressed is in connection with the data in field 445 of the card in Fig. 2. In this figure the space is blank, whereas in Fig. 3 it contains a "9" and in Fig. 7b it contains a "7". These characters are arbitrary, and determine whether the machine shall add, subtract or take a total. For instance, if the card presented at the sensing station represents a newly issued policy, the amount of the policy is to be added to the amount of insurance in force. The field 445 will then be

left blank and the machine will perform the proper adding function. If the card represents a death, a "7" will be printed in this field and the amount of the policy will be subtracted from the amount in force. If the card is a balance card the field will contain a "9" and the amount will be added, after which other agencies will cause the machine to take a total. The control by these arbitrary characters is effected by the sensing pins 181 cooperating with the appropriate hole spaces and controlling the setting of certain combs. Thus, if the field is blank or contains a "7", the combs 446 (Fig. 85a) will permit the feeler bar 447 to advance. This bar has a projection 449 adapted to actuate a bell crank 450 fixed on a rod 451. The bell crank is thus turned to the position of Fig. 85 and locked there by a latching plate 452. The turning of shaft 451 will, through a lever 453 having pin and slot connection with a link 454 (Fig. 17) connected to member 422, pull said member to the left so that the paper feed will be suppressed.

The parts having been locked in this position, will prevent printing until released. Thus, if several cards representing new business, etc., are passing through the machine, transmitting their data to the accumulators, no printing will be effected. After the passing of this group and the balance card belonging to the group, a bail 455, actuated in a manner presently to be explained, will raise the combination combs slightly. A special blank comb 456 will then lift a roller 457 into a notch in the latching plate 452 and move the latter to the right against the action of spring 458 and release the bell crank 450 so that the parts will be released for paper feeding.

Fixed on each link of the shaft 451 is one arm of a toggle 460, the other arm of which is connected to block 461 fixed on a bar 462. When shaft 451 is rocked to the position of Fig. 85 the bar 462 is raised. This bar extends crosswise in the machine under all of the hammer releasing members 342 (Figs. 24 and 86). The raising of this bar holds all of members 342 in the position of Fig. 24 so that none of the hammers 301 can be released for printing.

When the member 422 is tilted other than through the link 454, it will, of course, actuate said link, but it will not cause the bar 462 to be raised by reason of the pin and slot connection between lever 453 and link 454.

A tape 464 (Fig. 23) connected at 465 to the platen carriage and to a spring drum 466 on the machine frame serves, in the well known manner, to shift the carriage to the left when released. When in normal position, the carriage is to the right of the position shown in Fig. 23, with the cam 435 cooperating with the lever 436 as we have seen. The carriage is held in such position by one

of several stops 467, on a rod 468 attached to the carriage 365, cooperating with a fixed stop piece 469. The stops 467 are held up and in contact with the fixed stop 469 by a spring 470 (Fig. 17) acting to rock the shaft 468. On shaft 471 (Figs. 20, 52) which is actuated by one of the cams on shaft 392 is a lever 472 connected to a link 473 reaching upwardly and connecting with a lever 474 (Figs. 17 and 23) loose on the shaft 419. Said lever is connected to a bifurcated lever 475 fixed on a shaft 476. This shaft has another bifurcated lever 477 (see also Fig. 34) adapted to actuate a lever 478 to depress a slide 479. This will depress the stop 467 and thus free it from the fixed stop 469, permitting the carriage to move to the left until the next one of stops 467 engages the fixed stop 469. A retaining pawl 480 may be provided 20 to prevent rebound of the carriage when it is stopped. Also, to retard the speed of the carriage when it is released, a governor may be provided. This may comprise a flyweight 481 (Figs. 33 and 35) connected by reduction gearing 482 to a rack 483 on the carriage.

After the carriage has been released several times, controlled by the cam on shaft 392, to present successive columns on the report sheet for printing, and after printing has been effected in the last column, the carriage will be released once more. At this time, a block 484 on the rack 483 will strike the clutch lever 485 and close the clutch 486. 35 As we saw in Fig. 36, the rod 41 is constantly turning. The closing of the clutch then, will actuate the bevel gears 487, and through the rack 483, return the carriage toward the right to its normal position. When this position 40 is reached, another block 488 on the rack will strike a lever 489 and cause the opening of clutch 486.

The connection of the rack 483 to the carriage 365 is by means of flanged pins 490 45 engaging in slots 491 in brackets 492 fixed to the carriage. A spring 493 normally holds the rack to the left as in Fig. 23, but when clutch 486 is closed, the inertia of the carriage will cause it to lag while the rack moves to the right the distance of the slots 491. In the meantime, the spring 493 starts the carriage and when the pins 490 reach the ends of their slots they will move the carriage. Fixed on the rack is a cam 494 cooperating with a lever 495. The normal positions of the parts is shown in Fig. 23. When the rack is thrust ahead of the carriage, the cam actuates the lever 495 as in Fig. 33 and through link 496 (see also Fig. 17), rocks shaft 468, depressing all of the stops 467 so that they may pass freely under the fixed stop 469 during the return of the carriage. When the clutch 486 is again opened, the rack, being released, quickly returns to normal position under pressure of spring 493, thus releasing

lever 495 and stops 467 so that the latter may quickly cooperate with stop 469 to hold the carriage in normal position.

Finder

The finder is adapted to take a reading of information in certain perforated fields on the cards as they are fed through the machine and hold this reading in suitable mechanism.

If the readings on succeeding cards do not change the finder will permit the normal operation of the machine, wherein other information is taken from the card and placed in predetermined accumulators.

If the reading of a card does not agree with the reading set-up in the finder by the previous card, the finder will cause the operation of mechanism for recording upon suitable record sheets information contained in accumulators as described.

It is understood that cards fed through the machine are grouped according to a certain classification and this group sub-divided under other headings.

Thus, cards 10 and 18 (Figs. 2 and 3) may be grouped according to information contained in field 16. Cards with similar designations in this field may be again grouped to divide the cards according to field 17. Cards having the same designation in field 17 may be again sub-divided according to either field 14, 803, 803a, 801, 802 or 802a.

The last card in each of these last groups to be fed through the machine is the balance card 18, containing a summary of all similar cards at a previous parting.

Referring to Fig. 55 the sensing pins 181 butt against lateral projections on the ends of bar 804 and hold them in the position shown, against the pressure of springs 805. 105 Each of the bars 804 has an upwardly projecting arm 806 adapted to engage notches 807 in slidable combs 808.

Combs 808 are mounted in frame 809 suited to be raised vertically to disengage the notches 807 from arms 806. The combs 808 have each a cut 810 which when all the combs are in alignment will allow a cross-bar 811 to swing about rod 812 in a counter-clockwise direction.

Thus, to put a reading into the combs 808 the frame 809 is lifted. As shown in Figs. 42 and 55 a vertical link 810a having a universal connection with arm 811b loose on shaft 812a is adapted, when pulled downwardly to engage a projection 813a on an arm 813 fixed to the shaft. As viewed in Fig. 55, this will turn the shaft 812a clockwise.

In Fig. 58 the frame 809 is carried by links 814 and 815, fastened to levers 816 and 817. The clockwise motion of shaft 812a will, through cam 819 raise rod 820, which actuating levers 816 and 817 will rock them about their centers to raise frame 809 from the position shown in Fig. 55.

A vertical member 821 is adapted to move vertically, guided by stud 822, and actuated by a roller 823 on cam 819, cooperating with a slot in member 821.

5 Pivots mounted on the main frame of the finder are levers 824 and 825 which carry at their upper ends cross angles 826 and 827 held in inoperative position by springs 828.

When roller 823 pulls member 821 downward, studs 829 mounted on said member engage the lower ends of levers 824 and 825 and turn them clockwise and counter-clockwise respectively. This causes cross angles 826 and 827 to move inwardly and align the combs 15 808. Spring pressed latches 830 may be provided to engage pins 831 on levers 824 and 825 to hold them in the position shown in Fig. 58 until when the frame 809 is lowered and a pin 832 on member 821 strikes the latches 830 20 and disengages them, allowing springs 828 to withdraw cross angles 826 and 827.

While the combs are in the restored position shown in Fig. 58 certain of the pins 181 25 may have advanced through holes in the card and will allow springs 805 to urge bars 804 forward to the dotted position. While certain of the bars 804 are in this advanced or reading position the frame 809 is lowered, permitting the foremost notch 807 to engage 30 arm 806.

Upon restoration of the sensing pins, the bars 804 will move to the left as viewed in Fig. 55 and will carry with them combs 808, moving certain cuts 810 out of alignment.

If the next card to be sensed by the pins 181 has the same perforations in the aforementioned fields the same bars and combs 804 and 808 which have been moved to the left will be permitted to advance and re-align 40 cuts 810. This will allow bail 811 to enter.

Should the perforations in the card sensed be unlike those on the previous card, one or more of the bars 804 which have been moved to the left will not be returned, or some bar 45 which has not been moved to the left may be advanced to the right. This will cause disarrangement of cuts 810 and bail 811 will not be permitted to swing upward.

Levers 833 loose on rod 834 have pin and 50 slot connection with members 835 slidably mounted in cross bars 836. See Figs. 55 and 11.

Clockwise motion of levers 833 will move members 835 to the left against projecting 55 ends of bars 804 and hold them inoperative.

Thus, perforations in those fields on the card for which bars 804 are held inoperative are prevented from controlling the finder, but unless pins 181 are also held out, the data 60 in those fields may appear on the record sheets.

In Figs. 42 and 61, the bail 811 is adapted to operate in cuts in the outer banks of combs controlled by pins in fields 14, 803, 803a, 801, 802 or 802a, of cards 10 and 18, Figs. 2 and 3.

A change in any of these fields would disarrange the cuts 810 and prevent the rising of bail 811. This inability of bail 811 to rise will cause the machine to stop, or in the case of automatic operation, to take an age total 70 on sheet R2. As viewed in Fig. 42 this mechanism is located on the left side of the finder.

A shorter bail 811a is adapted to operate in cuts in the inner bank of combs controlled by pins in fields 16 and 17 of cards 10 and 18. 75

The inability of bail 811a to rise, due to disarrangement of its controlling combs will cause mechanism on the right of the finder to stop the machine, or automatically take a kind total as the case may be. 80

Fig. 61 shows the bail 811a carried on a sleeve 837, bail 811 being fixed to rod 812.

Referring now to Figs. 42, 56 and 57, a lever 838 is adapted to be rocked about its axis through a universal connection with an arm 839 on oscillating shaft 112. A link 840a connecting a cam 840 to lever 838 will also cause the cam to rock. A roller 841 on bell crank 842, which is fixed to the rod will ride on cam 840 and through spring connection will tend to turn latch 843. Arm 845 also fixed to this rod is link connected to bail 811. 90

Similar elements tend to rotate bail 811a on the opposite side of the finder. 95

A spring 846 tends to turn the bell crank carrying bail 811 counter-clockwise while a similar spring 847, Fig. 55, tends to turn bail 811a in a similar direction.

A member 848 adapted to move with cam 840 through the medium of spring 849 and pin 850 has a lateral projection 851 at the end of one of its arms which will engage latch 843 when the latter is in its operative position as shown in Fig. 57. 100

When the cam 840 turns clockwise, if the bail 811 is free to rise into a clear opening, it will turn latch 843 into the path of member 848 and prevent its further motion. A further clockwise motion of cam 840 will turn bell crank 842 counterclockwise and through arm 845 withdraw bail 811 so the sensing pins may be restored at this time in the operation of the machine. Member 848 is prevented by latch 843 from moving further with cam 840. 110 A vertical link 592 is connected at its upper end by a universal joint to another arm on member 848. The distance that link 592 has moved due to the change of position of member 848 from Fig. 56 to Fig. 57 is not sufficient to cause the operation of totaling mechanism. 115

Should a disagreement occur in the combs 808 and prevent the bail 811 rising roller 841 directly connected to the bail 811 will not ride on to the low portion of the cam 840 and latch 843 will remain in the position shown in Fig. 56. The projection 851 in its downward movement will not be stopped and will continue until a tail on member 848 strikes a pin in the finder frame. This fur 120 125 130

ther motion of member 848 will depress link 592 sufficiently to engage bell crank 593 (Fig. 41) and cause totaling mechanism to operate.

Should bail 811a fail to rise similar mechanism on the other side of the finder will further depress vertical link 589 (Fig. 42) to initiate other totaling operations.

Depending from the tail of cam 840 (see Fig. 56) is a link 852 adapted through pin 10 and slot connection to rock lever 853 about its axis. A vertical link 854 mounted in suitable guides is actuated by means of lever 853. A block 855 fastened to link 854 striking the base, is adapted to limit the downward motion of said link.

The continuous up and down motion of link 854 takes place while the machine is taking a total and functions to stop the machine as has heretofore been shown.

20 In Figs. 42, 55 and 59, the two bars 804a which are controlled by the pins 181 which sense perforations in the two upper rows of the field 445 of the card 18, Fig. 3, carry projecting pins 856 fastened near their left ends.

25 As will be observed, the pins controlling these bars 804a will not advance unless the card presented at the sensing station is a balance card 18. Cards 10, not having perforations in these two spaces, will not cause movement in the bars.

30 In Figs. 55 and 59, a plate 857 having slots 858 is adapted to move vertically, guided by rods 834 and 834a. Notched shoulders 859 in plate 857, when in lower position of Fig. 55, are beneath pins 856. Forward motion of bars 804a would position pins 856 above shoulders 859 and prevent the upward motion of plate 857 when released.

35 Thus can be seen that a card 10, Fig. 2, 40 would not cause pins 856 to advance and would allow plate 857 to rise to the position shown in Fig. 59. Whereas a balance card would prevent the upward motion of said plate.

45 A fixed guide plate 860 having suitable guide slots for pins 856 may also be provided.

50 As has heretofore been shown link 755 (Figs. 56 and 12) is adapted through pin and slot connection to be moved horizontally by bell crank 192. Link 755 is fastened at its other end to a lever 861 fixed on shaft 862 and carrying at its lower end a pin 863 spring-pressed against which is a latch member 864 loose on shaft 862.

55 A vertical stop-link 865 pivoted on stud 866 and held in a vertical position against screw 867 by spring 868 is positioned in the path of a pin 869 on member 848 to intercept the clockwise rotation of said member.

60 In Figs. 42 and 55, the shaft 862 has fastened to it an arm 870 and a forked arm 871 which is connected to the plate 857. Thus, the presence of a card 10 in the sensing station, permitting plate 857 to rise, will allow

link 755 to turn shaft 862 clockwise through lever 861.

Through pin 863 in lever 861, the latch member 864 is also turned clockwise and a pin 872 on said member engages a shoulder on a spring-pressed latch 873 pivoted on stop-link 865.

70 Thus, when link 755 is urged to the left (Fig. 12) by the clockwise rotation of bell crank 192 to restore the sensing pins 181, 75 said link will, through spring connection with latch member 864 and latch 873, turn stop-link 865 clockwise out of the path of pin 869 in member 848. A latch 874 will hold stop-link in the position shown in Fig. 57. 80

85 The presence of a balance card 18 in the sensing station preventing the plate 857 from rising will prevent the turning of shaft 862 and through failure of mechanism just described to function will not move stop-link 865 out of the path of pin 869. This will prevent motion of link 755 as heretofore mentioned.

90 From the foregoing will be seen that the very first card to be sensed by pins 181 will disagree with any reading in the finder combs 808. This will cause links 592 and 589 (Fig. 42) to be both depressed, causing mechanism to either stop the machine or take a total automatically as the case may be. This will cause any information contained in the accumulators to be printed and the accumulators cleared for subsequent tabulating. 95

95 While this is taking place, the first card is held at the sensing station, and at the 100 end of the totaling operations, when the finder combs are raised and aligned, they will descend to take a reading of said card.

If this first card is a new card 10 it will 105 through plate 857 and cooperating mechanism, rock stop-link 865 out of the path of pin 869 on member 848.

Succeeding cards in this group being alike the latch 843 will intercept member 848 since stop-link 865 is held in its oblique 110 position by latch 874. When the first card of the next group appears at the sensing station, the link 592 will be depressed sufficiently to operate aforementioned mechanism to stop the machine or take an age total on record sheet R1, Fig. 6.

115 Referring now to Fig. 42, when a total is taken shaft C7 is turned counterclockwise and the arm 650 at the end of its downward movement will cooperate with a pin in link 120 875 to pull said link down against the tension of spring 876.

125 In Fig. 56, link 875 is fastened at its upper end to a plate 877 loose on shaft 812a. Clockwise rotation of plate 877 will cause pins 878, oppositely disposed on an axis of said plate, to turn latches 874 and 873 counterclockwise and clockwise respectively to allow stop link 865 to assume an upright position.

130 If the first card of the next group is a

balance card 18 (if there has been no change in the amount of existing policies for that group, since the previous posting, there will be no new cards 10 present) stop link 865 will intercept pin 869 and prevent the machine taking a total. The data on card 18 will be added to the kind accumulator A5 and printed on sheet R1 directly from the card 18.

Referring now to Figs. 42 and 55, a lever 879 mounted loosely on shaft 112 has a roller 879a adapted to be actuated by a cam 880 on shaft 119. Said lever actuated by cam 880 and spring 881 is adapted through suitable linkage and bell crank 881a to rock a lever 882. A latch 883 is adapted to engage a pin in lever 882 and hold it in the position shown against the tension of spring 881.

Referring to Fig. 55, the clockwise rotation of shaft 862 due to plate 857, as we have seen, rocks arm 870 which through a link at its end rocks a lever 884 to depress a member 885. A pin 885a in said member will trip latch 883 and allow lever 882 to turn clockwise. Another pin 885b in member 885 will engage the upper edge of hook 886 and depress it as shown in Fig. 59. The counter-clockwise movement of lever 882 under control of cam 880 will now pull hook 886 to the left and through connection with shaft 812a will turn said shaft clockwise to restore the finder combs 808.

A by-pass 887 on hook 886 is adapted, when said hook is pulled to the left, to assume a position to the left of pin 885b in member 885.

In Fig. 56 a spring 888a is adapted through arm 889a fixed to shaft 812a to turn said shaft counter-clockwise to its restored position.

This motion of shaft 812a will pull hook 886 to the right and by-pass 887 being to the left of pin 885b as viewed in Fig. 59, will engage said pin to turn member 885 counter-clockwise about its axis. This will cause pins 885a and 885b to release latch 883 and hook 886 respectively and allow their springs to return then to normal position as in Fig. 55.

Another pin 885c on member 885 will now be engaged by a shoulder 888 on a latch 889 which is spring held against said pin.

A member 890 having a lateral projection adapted to engage latch 889 will, when turned counter-clockwise by rod 891, allow member 885 to return to its upright position as in Fig. 55. Rod 891 is fixed to and rocks with latch 874 when a total is taken.

As we have seen, when successive balance cards pass through the machine, indicating no change from the previous posting totaling mechanism is not brought into operation and link 810a is not depressed to restore the combs 808.

The first new card 10 to be sensed then, will cause the mechanism just described to reset the finder combs and allow them to take the reading of said card. Should a change

occur hereafter, the machine will go through its totaling operations.

In Fig. 12, a lever 892 connected by means of a link 893 to an arm 894 loose on shaft 812a (see also Fig. 56) is adapted to engage a projection on arm 889a fixed on said shaft to turn it clockwise against tension in spring 888a to restore the finder combs.

Upon release of lever 892 spring 888a will return shaft 812a to normal position.

Accumulator unit

Each of the type bars 294 is attached at 501 (Fig. 65) at its lower end to a depending accumulator bar 502. Each accumulator bar 83 has attached thereto, slideable up and down on pins 503, a plurality of racks 504, 505, 506 and 507. The rack 504 is adapted to actuate the wheel 508 of each of three accumulators A1, A2 and A3. The rack 505 is adapted 83 to actuate accumulators A6, A7 and A8. Rack 506 actuates accumulators A4 and A5, and rack 507 actuates accumulators A9 and A10.

The entire bank of wheels 508 of each accumulator is carried on a shaft 520, (see also Fig. 68) and each wheel is free to rotate independently. The shaft 520 is supported at opposite ends by lever arms 521, 522 (see also Fig. 72) loosely carried on shaft 523. Arms 521 and 522 are connected by springs 524 to the frame 525, and tend to move the wheels into mesh with their racks. They are normally held out of mesh, however, by an extension 522a of arm 522 resting as seen in Fig. 72, on a shoulder of latch 526. A cam follower roller 527 on arm 522 will, when a cam bar 528 (see also Fig. 64) is in its lower position, also hold the wheels out of mesh. The latch 526 is normally held in locking position by a spring 529. An actuating lever 530 fixed on shaft 531 is connected by a link 532 to an arm 533 on shaft 523. This arm together with an arm 533a and a cross bar 536 constitutes a bail, the function of which will be described presently. The bail carries a cam follower 534 cooperative with a cam bar 535. When said cam bar descends, the bail will turn under pressure of spring 537 (Fig. 63). This will cause lever 530 to engage a pin 538 on latch 526 to release lever 522. A bent-over portion at the upper end of the latch will then snap over a spring-pressed latch 539, as in Fig. 72a, to be held in such position after the cam bar 535 rises. Now, when the cam bar 535 rises, arm 522 will turn under pressure of its spring 524 and move the accumulator wheels into mesh with the racks 505, etc. During this turning of arm 522, a pin 540 thereon will depress latch 539 and release latch 526 as in Fig. 72b, so that when cam bar 535 again rises the latch 526 may move into position to latch arm 522 as soon as the wheels are demeshed by descent of cam bar 528.

In order that the drawings may be clear, not all of the parts of the accumulator mechanism are shown in any one figure. Turning, then, to Figs. 69 and 70, additional mechanism is shown. Here, a spring-pressed locking or centralizing member 541 loose on shaft 542 is shown. When the wheels are in inoperative position they are held against accidental turning by said centralizing members. But when they are in mesh with the racks (Fig. 78), they are disengaged from said members.

To effect carrying from one wheel to the next higher wheel, each wheel has fixed to the side thereof, the usual carrying tooth 543 (Fig. 78a), adapted, when turned counterclockwise as viewed in this figure, to engage, once each revolution, an offset lever 544. This lever will thus be turned upon its axis 545 against the action of a spring 546, and will in turn, actuate a spring-pressed latch 547 to release the carrying latch 548. Referring now to Fig. 65, it will be seen that the carrying latches are normally all out of the paths of the lugs 549 on the racks 504, etc. The condition of these particular parts is shown in Fig. 70. The rear end of the carrying latch is held by a spring 550 against a bail 551, fixed on shaft 531. When lever 530 displaces latch 526 as heretofore set forth, it also turns shaft 531, (Fig. 72). This turns bail 551 clockwise in Fig. 70 to the position of Fig. 78a, turning latch 548 into the path of the lug 549. The spring-pressed latch 547 (Fig. 78) will then hold latch 548 in such position.

Now when the cam bar 535 rises and returns bail 551 the latches 548 will remain in the latched down position. Should any of the carrying lugs 543 turn far enough to actuate lever 544 the latter will in turn move latch 547 to release the carrying latch 548 which will then be actuated by its spring 550 and be drawn out of the path of lug 549. This lug 549, as is well understood, is on the rack which controls the wheel of the next higher denomination so that when said rack descends it will not be checked by the latch 548 and will advance a step farther to turn its accumulator wheel one unit farther.

To print a total from the accumulators they are brought into mesh with their respective racks before the latter rise. Then when the racks rise, turning the accumulator wheels the lugs 543 will eventually engage the upper portion of pawl 544 and be stopped thereby, thus checking the rise of the racks 504 etc. This in turn fixes the position of the printing bars to select the type to be printed.

Referring now to Figs. 63, 65, 68, 69 and 71, the arms 521 and 522 which carry the shaft 520 and wheels 508 are each provided with a link 553 reaching back through the back frame 554 and connecting to levers 555 which in turn are fixed on a shaft 556 oper-

ating in bearings 557. This connection serves, when cam bar 528 (Fig. 72) actuates follower 527, to transmit the motion around to the opposite end of the accumulator shaft so as to insure parallel motion thereof.

As shown in Fig. 63 an adjusting screw 558 may be provided to adjust the distance which the accumulator wheels may move toward or into their racks. In the printing of the totals from the accumulators the paper carriage is stepped laterally as will herein-after be pointed out and in each position data is printed upon the paper. This data is taken from the several accumulators. Means are then provided for selecting the accumulators which control the printing during the successive printing operations. This selecting means comprises in part a system of notched discs to be described later.

In Figs. 73, 73a, and 73b are shown three views in different positions of the units wheel and associate parts of the accumulators that are adapted for addition of complements only. When the first set of complementary digits is run into these accumulators, the complement in the units column is based upon nine as the sum, and thereafter until the accumulator is cleared, the complement in this column is based upon ten as the sum. In all other columns the complement is based upon nine as the sum throughout. To control the units wheel, it is shown as having the carrying mechanism common to the other wheels. The manner in which the latch 548 is released in this instance is as follows: The latch arm 547a has a rearward projection 915. The arm 547a is normally in locked relation with latch member 548. When the accumulator is rocked into mesh for the first time, the lever 916 fixed on shaft 556 will be rocked from the position of Fig. 73 to that of Fig. 73a, tripping over the spring-pressed flipper 918. During this accumulating stroke the lug 549 is stopped by member 548. When the wheels are demeshed and the lever 916 swings outwardly, its pin 919 will depress the flipper 918 and rock latch arm 547a, releasing member 548, and locking member 547a in the position of Fig. 73b by spring-pressed latch 920. When a total is taken from these accumulators, 110

inasmuch as the wheels contain complements, the complements of these complements must be struck to obtain the correct data. This is done by taking a total in the usual manner: the accumulators in this instance being A6, 120 A7 and A8 (Fig. 65). The racks 505 will be stopped in accordance with the digits in the accumulator wheels. The type bar, however, will have gained a half tooth space lead before taking up the lost motion represented by the lengthened notch 925 in the rack, so that the type will be stopped a half tooth space higher than the rack and will present the complement of the digit in the wheel for printing.

At this time the cam 921, (Fig. 21) is operating, and will at the proper time rock follower lever 922 fixed on shaft 706b, (Fig. 54) with the lever 706a. This will raise link 706 and rock stud 926, pulling link 928 to the left, rocking rod 929. The latch 920 loose on this rod will then be struck by the shoulder 930 on lever 931 fixed on the rod; the shoulder engaging a pin 932 on the latch; and the member 547a will be released to latch member 548 when the latter is again rocked clockwise. Each of the rods 929 has a lever 933 thereon, the ones associated with the two upper accumulators having spring-pressed lost motion connection with an interconnecting link 934; the lower one having a pivot connection to said link. The latches 920 of the two upper accumulators are fixed to their rods 929. When the rod 929 of accumulator A8 is rocked, the latches 920 of the three accumulators will be tripped.

As has been pointed out, when a total is being taken the bars 656, 657, 658 (Fig. 65) are raised.

When the total is printed from the kind accumulator A5 on sheet R1, the data is returned to the accumulator in the following manner: When the rod 926 is rocked, (Figs. 54 and 90), it will depress a link 936 having resilient pin and slot connection with a lever 937 fixed on a stud 938. On this stud is also fixed a lever 939 which will be interposed in the path of a pin 940 on the bell crank 941, (Fig. 91), to prevent clockwise rocking of the bell crank. The bell crank is connected by a spring 942 to the member 522. Now when cam bar 528 throws the wheels out of mesh and is immediately raised, the spring 942 immediately moves the wheels back into mesh before the racks descend. The lever 939 is then restored to normal position so that after the accumulator controls printing on sheet R2, it may be cleared.

Whenever a minus item is transmitted to the "amount of insurance" and "No. of policies" sections of the age and kind accumulators, and complements are run into the wheels, the complement in the units wheel must be based upon ten as the sum, and upon nine as the sum in the other columns. It is therefore necessary, when the data is rolled into the wheels, that the units racks carry their wheels a tooth farther than do the other racks. To this end these racks, (Figs. 75, 75a) are normally held in position by tail pieces 985 pivoted to the racks and adapted to engage a bracket 986. When a minus card causes the bail 905 to move the member 906 to the right to drop the combs a half tooth space, pins 987 on said member will move the tail pieces 985 off from the bracket 986 and permit the units racks to drop one and a half teeth space. When the racks descend in mesh with the wheels, they will thus roll an additional "1" into the units wheels.

On this stroke the type bars descend slightly farther than the racks and release the member 906 which moves back to normal position. Now, when the type bars and racks rise during the next card cycle, the tail pieces 985 will slip over the bracket 986 to normal position. The tail pieces may be held against the type bar by a guide 988 fixed on the type bar.

After the kind accumulator controls the second printing and is taken out from the racks, the data taken therefrom may be run into accumulator A9 to obtain a progressive total, such as shown on lines 748, 749, 750 on sheet R2, (Fig. 5). This is accomplished in the following manner. The accumulator A9, Figs. 64, 66 and 67, which may be used for this purpose is shown as controlled by a cam plate 945 slidably attached to the cam bar 528 and adapted normally to move up and down therewith; a latch member 946 being provided to cooperate with pin 947 to hold the plate in the position shown in Fig. 64. As the cam bar moves down and up, normally the accumulator A9 does not mesh with the racks because it has not been selected. When the discs 709, 710, Fig. 80, selects the kind accumulator for its second printing operation, that is, to print the total on the report sheet R2, the combination of notches in the combs 723, etc., is such as to also select the accumulator A9. This accumulator, however, will not mesh with the racks for the upward stroke of the type bars because of the reversed condition of the cam plate 945. After the racks have risen, however, and the cam bar 528 operates to clear the kind accumulator A5, it will release the accumulator A9 so that it will now mesh with the racks and upon the restoration of the type bars receive the data just taken from the kind accumulator. At the end of the downward stroke of the type bars when the cam plate 528 operates, it will take the wheels of the accumulator A9 out of mesh with the racks.

In order that carrying may be effected in the accumulator A9 at this time, it is necessary to permit the rack 507 to drop back the one tooth space which it was raised for the totaling as heretofore pointed out. This may be effected in the following manner: When the rod 706, Figs. 54, 77 and 77a rocks the lever 927 clockwise it will actuate the lever 948 pivoted at 949 on a bracket 950. This latch is carried with the bars 656 and 658, normally holds the bar 657 even with bar 656 as shown in Fig. 77. When the latch is actuated to the position of Fig. 77a, the bar 657 drops to the position of Figs. 77a, so that when the rack 507 descends the carrying lug 549 may pass the carrying latch 548 as in Fig. 77a, if said latch has been moved to carrying position. In order to strike the total standing upon this accumulator, lever 952, Fig. 21, is depressed from the position

shown. This in turn will depress a link 953 to rock a lever 954 fixed on the shaft 955 (see also Fig. 53); fixed on said shaft is a bell crank 956, Figs. 63 and 90, connected by a link 957 to a latch 958 adapted to be moved from the position of Fig. 63 to that of Fig. 90. We have already seen that to take a total the total key is depressed and then the start key when taking a total manually. Presuming this to have been done, now the shaft 72 as we have seen will operate. This shaft carries a lever 959 having a pin 960 adapted to rock a bell crank 961 to depress the latch 958. Thus when the latch is in the position of Fig. 90, depression thereof will rock a lever 962, fixed with respect to latch 526.

This will permit the accumulator to mesh when the cam bar 528 operates. At the same time that the lever 956 is rocked, it will raise a link 963. This as shown in Figs. 71, 93, 93a will raise a latch 964 from the position of Fig. 93 to that of Fig. 93a to prevent the bail 965 from following plate 695 under action of spring 966 to position to lock the type bars 294 against operation. The particular type bars with which this bail is associated are free to rise during the first cycle in this instance under control of the accumulator A9 and the printing will be effected in the usual manner 25 during this stroke. When the type bars descend the data taken from the accumulator will be returned to it. When it is desired to clear the accumulator the lever 952, Fig. 21, is depressed a greater distance than for merely 30 striking a total. This as will be seen in Figs. 63 and 90 will cause the pin 967 to actuate a lever 968 loose on shaft 955 and held against said pin by a spring 969 to move a link 970 a greater distance than heretofore, taking up 35 the lost motion connection with lever 971 and moving the latter clockwise about its pivot. This will rock lever 972 clockwise moving link 973 to the left rocking the lever 974 about its pivot 975 and slide the latch 40 frame 946 to the right from the position of Fig. 64 to that of Fig. 66 to release the cam plate 945. At the same time that this happens a latch 976 will be moved from the position of Fig. 64 to that of Fig. 66 to hold 45 said cam plate in this position while the cam bar 528 descends. When said bar reaches its depressed position the pin 977 being in the upper part of its slot will permit the spring 978 to move the frame 945 to the left as 50 shown in Fig. 67 and the pin 947 will lock the parts in this position as shown in Fig. 67. This will occur during the first totaling stroke so that in this instance the striking of 55 the total is not effected during such stroke, but will be effected on the second stroke. On the second stroke the cam bar 528 will rise carrying the cam plate 945 and permitting the accumulator to mesh. The type bars 60 will then rise printing will take place, the

cam plate will then descend to demesh the accumulator and the type bars will return.

Distribution of data

For each of the columns on the report sheet 70 R2, (Fig. 5) there is a corresponding accumulator (Figs. 63, 64, 65), each accumulator being adapted to control the printing of the data contained therein in the corresponding column. The accumulators may then be 75 cleared for their next operations. The accumulator A10 is adapted to accumulate data from individual cards of a group and a balance card showing past data of that group, and when a change in the group, as for instance the age group of cards occurs, print the accumulated data in the column B10, line 730 for instance, of the report sheet R1, (Fig. 6). This, it should be understood, takes place before the printing has taken place 80 from accumulator A5, the accumulator is cleared for accumulation of items of the next age group, and these results are printed in the same column.

While the accumulator A10 is accumulating data from successive age groups, and clearing after printing each group, the accumulator A5 will be accumulating the same data without clearing, thus compiling a 85 grand total of several age groups. This 90 accumulator will then control the printing shown in line 730a of sheet R1. This will represent the total of the items for the several age groups of that kind group. The accumulator A5 will not be cleared at this time, but will remain in mesh with the racks while the type bars are restored; the data thus 95 being restored to the accumulator for printing on the sheet R2. While it has been 100 stated generally that accumulator A10 accumulates data from the cards, more specifically, some items are added, as where the card represents a new policy, or one changed from another group to the group under consideration, and other items are subtracted from 105 the accumulator, as where the card represents a discontinued policy or one changed to some other group. This accumulator, then, 110 computes the existing status for each age group, while the accumulator A5 has to do 115 with the kind groups.

While the accumulators A10 and A5 are computing the existing status, the data on each card is also being sent to one of the other accumulators, depending upon whether the card represents a newly issued policy, a 120 death, or other conditions represented in the several columns on sheet R2.

After a change takes place in the kind group, and the total is printed on sheet R1 from the accumulator A5 and rolled back into the accumulator, the platens are then shifted, and the accumulator A5 again brought into operation; this time to print its 125 data in line 731 on sheet R2. The carriage 130

is then shifted step by step to present the successive columns on the sheet to printing position, and the proper accumulator brought into play at each step to print its data in the column.

Where no changes have occurred in certain groups between the making of reports, there will, of course, be balance cards for such groups unaccompanied by new cards.

10 In order to save time in the machine operation, the data on the balance card is not applied to the age accumulator, but is printed directly on the sheet R1. The data is applied in the usual manner, however, to the kind

15 accumulator A5.

Presuming the machine to have been started and the card 10, Fig. 2, to be at the sensing station, the pins will advance to take their readings. The perforations in the field 20b

20 will now determine which accumulators shall receive the data taken from the cards. The perforations in the field 19a also come into play at this point. That is, the perforations in field 20b will determine whether the data

25 shall be sent to the accumulators controlling the printing in column B10 as well as the accumulator controlling printing in column AA5, Fig. 5, and to the accumulator controlling one of the other columns on the report

30 sheet R2, or whether data shall be printed directly in the column B10 without having been run into the accumulator A10 and at the same time being run into the accumulator controlling the printing of column AA5.

35 The manner in which this is accomplished is as follows: The perforations in field 20b determine whether the card represents a plus or a minus item, that is whether it shall be distributed to columns AA6, AA7, AA8 on

40 one hand or columns AA1, AA2, AA3 on the other hand. The perforations in field 19a will determine which of the three in either group shall receive the data. This selection is accomplished through the pins,

45 feeler bars and combination combs heretofore described. These combs in the present instance determine the distance that the selector combs 723, etc., Figs. 63 and 80a, shall rise when released by the type restoring

50 bar 298. The upper portion 294a of these selector combs being operated and controlled similarly to the type bars 294, Fig. 24. The combination of notches 728 in the combs will determine which accumulators are to operate

55 when the latter are released to mesh with the racks. Referring to Figs. 6 and 68, the first five accumulator wheels 508 to the right in the accumulator, are positioned to operate in the field 740 of the report card R1, but

60 are locked out in the present instance so as not to operate. The next accumulator wheel is adapted to control the type bar operating in column 741 to print an asterisk under certain circumstances hereinafter described. The next 11 wheels, counting toward the left,

control the type bar operating in the column designated "Amount of insurance". The next 7 wheels control the type bars operating in the columns designated "No. of policies."

At the places of demarcation between these

70

several columns, the carrying lug on the rack bars may be omitted so as to split the accumulators to prevent carrying from one section into the next. Beginning now where we left off with the accumulator wheels, the next of these wheels working toward the left have no carrying mechanism, but are, of course, provided with the usual zero stop devices. The first two of these wheels on the right control type bars operating in column 742, the next 2 in column 743, the next 2 in column 744, the next 5 in column 745, the next 2 in column 746, the next 6 may control type bars operating in field 747, but are not brought into operation here. The items included in the various columns on the report sheet R1 are taken from the cards shown in Figs. 2 and 3. Other items included on these cards may be suppressed by the operation of the appropriate ones of the levers 215 as heretofore described. As elsewhere stated the cards are stacked according to age and kind classifications, each group followed by a balance card showing the prior status of the group. The new cards represent changes that have taken place since said balance card was compiled. These new or change cards run through the machine first, the data thereon being run into the accumulators. Then

100

when a balance card is presented at the sensing station, the data thereon is applied to the proper accumulators. The totals are then printed on the report R1, the age of the insured, shown as 22 in this instance in the first line, is taken from the first card of the group and applied to the accumulator wheels which are then locked against further operation until the printing takes place at which time the parts are released for printing operation. This is also true of the year and

105

kind designation. The number of policies is determined in a manner which will presently be described.

After the year and kind designations have been printed on the sheet R1 from the age

115

accumulator the latter is cleared and these particular wheels and type bars suppressed until a kind change occurs. At the same time that the year and kind designations are applied to the age accumulators, such data is also applied to the kind accumulator A5, the

120

operation of the parts being then suppressed until a change in the kind group occurs. When the latter change occurs the several totals printed in the "Amount of insurance" column, having been progressively accumulated by the accumulator A5 are now printed as shown on the line 730a. The total number of policies is also printed on this line.

125

The report sheet R2 is then brought into

130

printing position and the data taken from the several accumulators and distributed in the appropriate columns. After this has taken place the accumulators clear and operation commences upon the first age group of the next kind group. When the data is taken from accumulator A5 and printed in the column AA5 and the accumulator cleared, the accumulator A9 is then brought into mesh with the rack 506 and the amount taken from accumulator A5 rolled into the accumulator A9 to obtain a progressive total. The cumulative total in the accumulator A9 may be printed at any time by operation of the appropriate levers and start key. This total will be printed as on lines 748, 749 and 750.

The data in the column designated "No. of policies" on sheet R1, is derived in two ways: First by counting the new cards as they pass through the machine; and second, by adding to the number thus obtained, the number represented in field 751 (Fig. 3), on the balance card. Ordinarily, for each new card passing through the machine, the accumulator is adapted to add "1," representing one new policy appearing in that class. There are occasions, however, where it is not desired to count a card; as for instance, where a single policy is split into two parts, requiring two cards, but representing only one policy. In such a case, one of the cards will have a hole in the bottom space in field 20a, Fig. 2. The sensing pin which cooperates with this hole space is shown at 752, (Figs. 24, 82 and 82a).

Referring to Figs. 24, 83, 84, a suppressing plate 753 is normally in the position shown in Fig. 24 disengaged from the combs 233. In operation these plates are moved a short distance to the right as viewed in Fig. 84. This will prevent this group of combs 233 from operating with the exception of one of the combs 754, Fig. 83, this being the comb which controls the unit column of the number of policies data. This partial movement is effected as follows: Each time the sensing pins are released by counter-clockwise movement of bell crank 192, Fig. 12, a link 755 having pin and slot connection with said bell crank, is moved to the right. This link carrying a pin 756 adapted to actuate a lever 757 fixed on a shaft 758. This shaft is then rocked clockwise, Fig. 82a. Fixed on said shaft is a lever 759 having a pin 760 engaging the back of lever 761. The foregoing movement will carry the lever 761 from the position of Fig. 82 to that shown in Fig. 82a. The lever 761 is fixed on a rod 762 on which is fixed a lever 763 connected to a link 764 connected to a spring-pressed lever 765 (see also Fig. 24) engaging the back of the aforesaid plate 753. Also fixed on the shaft 758 is a lever 766 extending above and below and connecting to links 767, 768. This link 767 will thus be moved to the right and the link 768 to the left. Pins 769, 770 will thus con-

trol the movement of the lever 771 to a centralized position rocking the rod 772 to a pre-determined position which in turn controls the positioning of the appropriate one of the stopped steps 229, Fig. 27, and this in turn will control the setting position of its combination combs 233. This particular comb is the one designated 754, Fig. 83. In this way the said comb is so set up as to control its feeler bars 262. This in turn will control the type bar 294 and will roll "1" into the appropriate accumulator wheel. Under the foregoing conditions the feeler pin 752, Figs. 82, 82a, did not advance. If now the said pin should find a hole in the card and advance, the parts would assume the movements described and the pin moving forward would actuate lever 761 a greater distance, moving the lever 765 a greater distance. This in turn moving the plate 753 a greater depth into the combination combs, Figs. 83 and 84. The plate 753 will now lock the particular comb 754 against operation and suppress the adding of the "1" or in other words, the counting of that particular card.

After the new cards have passed through the machine, and have been counted or not, under control of column 20a, the balance card is then fed in. This card will not be counted, as the finder will now prevent movement of the link 755, but the field 751 (Fig. 3) contains data representing the number of policies in this class when the last report was compiled. This data should then be added to the number of policies standing in the accumulator wheels. As neither the count nor non-count features are brought into play at this time, the plates 753 are disengaged from the combination combs 233 and the usual accumulating operation takes place.

There may also be occasions when the data on a card is not to affect the age and kind accumulators; that is, it is not to be added to or subtracted from these accumulators, as where a change in the policy does not affect the existing amount of insurance. In this case, a "2" or an "8" printed in the field 20 (Figs. 7a and 7d) will be accompanied by a perforation in the third from the top hole space in the corresponding position on the lower half of the card. Similar mechanism is controlled by a hole or the absence of a hole in this position.

Referring to Figs. 82, 82a and 83, the feeler pin 780 operates upon the space in question. If there is no hole in the space, the pin cannot advance, and the data goes to the accumulators either as a plus or a minus item. If there is a hole in this space, however, the pin 780 advances, and rocks the lever 761a, which causes lever 765a to move the plate 753a against the action of spring 781, into locking relation with the combination combs 233 associated with the amount of insurance type bars, etc. This will suppress the oper-

ation of the corresponding type bars and accumulator wheels.

We will now consider the manner in which the selection of the accumulators is effected.

- 5 In the column 445 on the cards in Figs. 2 and 3, are shown the letters "D", "C" and "B", meaning debit, credit and balance. If a "9" is printed in this column; the corresponding perforations appearing in the field 20b; the 10 card is a balance card. If a "7" appears in the column 445, as in Fig. 7b, the card is a debit card; that is, its data is to go to an accumulator corresponding to one of the three columns on sheet R2 designated "Debit 15 changes", "Discontinued" and "Died". It has already been seen that the same data goes to the so-called age accumulator A10, and to the so-called kind accumulator A5. Now, as to which of the three debit accumulators it 20 shall go to, and whether it shall be added to or subtracted from the data in the age and kind accumulators is determined by the arbitrary characters appearing in the column 19 (Fig. 2). If the character appears to the 25 left in this column, the data is to be added to the age and kind accumulators, and if it appears to the right of the column the data is to be subtracted from these accumulators. If the character at the right in field 19 is 30 a "3" as in Fig. 7b, the data besides being subtracted from the age and kind accumulators, is added to the "debit changes" accumulator, which is A8 (Fig. 65). If the character in this position is a "2" as in Fig. 7c, the 35 data will be added to the "Discontinued" accumulator, which is A7 in Fig. 65. If the character is "1" as in Fig. 7d, the data is added to the "Died" accumulator, which is A6 in Fig. 65. If the character at the left in field 40 19 is a "1" as in Fig. 7, the data besides being added to the age and kind accumulators, is added to the revival accumulator, A2 in Fig. 65. If the character in this position is a "2" as in Fig. 7a, the data will be added to the 45 "credit changes" accumulator A3; and if the field is blank the data, besides, being added to the age and kind accumulators will be added to the issued accumulator A1.
- The perforations in the field 19 control the 50 stepped stops 229a in the usual manner, and these control the combination combs 233a which, in turn, control the rising distance of certain of the accumulator selector combs 723, etc., (Figs. 79a, 80a).
- 55 As we have seen, every new or so-called change card, that is, every card other than a balance card, is accompanied by a clockwise rocking of shaft 758 (Figs. 82, 82a), and a consequent movement to the right of the link 60 767 against the action of a spring 782 attached to a fixed post 783. This movement actuates a lever 784 fixed on the rod 785 to rock said rod. This rod carries one of the stepped stop members 229a, (Fig. 15), associated with the combination combs 233a that

control the rising distance of the accumulator selecting combs 723, etc. One of the latter combs is thus controlled in this manner during ordinary accumulating operations.

Control mechanisms

70

Assuming the motor of the machine to be running, and consequently also the pulley 26, (Figs. 37, 41 and 54), the machine proper may be brought into operation by pressing inwardly, the start key 560, (Fig. 20). This, through a bell crank 561, raises link 562, connected to a bell crank 563a, (see also Fig. 16), similar to bell crank 563, which in turn is connected by a link 564a similar to link 564, to a lever 565 fixed on the shaft C4. This shaft will thus be rocked and, through a link 566 (Fig. 37), actuate member 35 to permit clutch member 33 to lock into the worm 29 which is running. This will cause sleeve 30 and parts connected thereto to operate.

75

Means are preferably provided to prevent the machine from starting until the worm 29 has attained a predetermined speed. This may comprise a centrifugally controlled member 567 (Figs. 38, 44 and 60), pivoted at 568 to the pulley 26. A spring 569 normally holds the member 567 inwardly toward shaft 27, but as the speed of the pulley increases, the member swings outwardly and will 95 eventually engage a roller 570 on a spring-pressed lever 571, turning the lever clockwise as viewed in Fig. 60.

80

Normally, the lever 571 engages in notches in bars 572 and 573, as shown in Figs. 38 and 54, preventing lateral movement of the bars. These bars are connected by levers 576, 577 fixed on rods C4 and C3, so that the rods cannot rock until the bars are released. A spring-pressed latch 574 will lock lever 571 in the outward position.

100

After the clutch 33 has been released, and shafts C3 and C4 returned to normal positions, and the motor turned off, the stopping of the pulley 26 will permit member 567 to be drawn inwardly by its spring. It will then engage a pin 575 on the latch, causing the latter to release lever 571. The lever will then rise into locking position with respect to bars 572, 573.

110

Referring to Fig. 43 when the start key is pressed and rod C4 rocks to operative position a lever 580 fixed on said rod will be rocked from the full line position to the dotted line position 581 and locked in the latter position by a latch 582 cooperating with a pin 583 on the lever. The latch is pressed into operative position by a spring 584. The rear end of latch 582 is provided with a spring pressed flipper cam 585 which when engaged by a pin 586 on a lever 587 turning clockwise on shaft C7, will depress the rear end of said latch to release the lever 580, thus permitting C4 to turn counter-clockwise under pressure of spring 588 on the start key, 120 125 130

Fig. 20. When the lever 587 turns counter-clockwise, it will turn the cam 585 about its pivot against the action of its spring without affecting the latch 582. Operation of the lever 587 is effected when a change in a group of cards occurs. This change is detected in the finder which depresses a link 589 having a pin 590 adapted to engage the arm 591 of said lever. Another link 592, Fig. 41, also 10 operated by the finder when a change of another classification occurs is adapted to depress a bell crank lever 593, which in turn will actuate a link 594 connected to the lever 587, so that depression of link 592 will also 15 effect stoppage of the machine. Referring to Fig. 39, rod C4 has fixed thereon a lever 595 which at its lower end has pivoted thereto a rocker arm 596 having a slot at each end adapted to engage pins 597, 598 on levers 20 599, 600 fixed on rods C6 and C2. Normally the rocker arm is in latched position with respect to lever 600 and unlatched from lever 599 so that when the start key is pressed the rod C2 is also rocked clockwise. This, as 25 seen in Figs. 37 and 44 will actuate the clutch link 74 to bring gear 42 into operation as heretofore described.

The machine is now running under control 30 of a group of cards accumulating the data contained on said cards. At the end of the group the finder will operate and stop the machine as described. Let us presume that the machine is stopped by depression of the link 592 of the finder. In order to take a 35 total of the items just accumulated the operator will press the total key 601, Figs. 20 and 21. A pin 602 on the total key which normally holds a lever 603 to the left now releases said lever permitting it to be pulled to the right by its spring 604. Lever 603 is 40 fixed on a stud 605 on which is also fixed a latch 606 which is now pressed upwardly against the start key 560 ready to latch over the shoulder 607 of the stop key when the 45 latter is again pressed. The total key is also provided with a locking shoulder 608 into which a latch 609 will move when the key is pressed, to lock it in operative position. Operation of the total key will actuate bell 50 crank 610 and raise link 611 actuating bell crank 563, pushing link 564 to the left and rocking the rod C3 clockwise. In Fig. 39, this rod is shown as connected by a goose neck 612 and a link 613 to the rocker arm 596 so 55 that this rocking of shaft C3 will reverse the position of the rocker arm from that shown in full lines to that shown in dotted lines, so that when the start key is pressed, rod C2 will not be actuated, but rod C6 will be. As 60 seen in Fig. 54, rod C3 also has fixed thereon a goose neck 614 having a pin and slot connection with a link 615 connected to a latch 616. When the rod C3 is rocked its pin will move to the upper end of the slot in link 615, 65 tensioning the spring 617, so that when rod

C2 is rocked as will hereinafter be described, the lever 618 will be locked in such moved position by the latch 616 as shown in Fig. 48.

The lever 577, Fig. 54, will prevent operation of the rod C3 when the speed of the motor is below predetermined value as in the case of the start key heretofore described. These operations set up the machine for taking a total but do not start the machine operating. This is done by now pressing the start key 560, Fig. 20. This key will now be locked by latch 606. In this case the latch 582, Fig. 43, although in operative position does not actually prevent the return of rod C4 as the latch 606 rocks the parts in such position that the pin 583 is slightly to the left of latch 582. During a totaling operation the finder will actuate lever 587 during each cycle of the machine so that lever 582 rocks during each cycle, but does not release rod C4. The actuation of the start key then besides throwing in the clutch 33, Fig. 37, will also, through rod C6, actuate link 63 and cause the clutching up of gear 55, Fig. 37, for rotation. We now have gears 31, 55 and 56 turning, but gear 42 is for the moment stationary. The drum cam elements 80, 81 are now being moved laterally as previously described to cause rocking of shaft C7. The effect of the rocking of this shaft will be described later.

When gears 55, 56 have turned 180 degrees, the pin 77 on gear 31, (Figs. 37, 44, and 47) will strike the cam lever 76 and through link 75 turn a lever 620 clockwise. This lever is loose on shaft C2 and is adapted to engage a turned over portion 621 of a second lever 622 fixed on said rod, thus the rod will also be rocked clockwise. At this time the rod C2 will be latched in this position as shown in Fig. 48 and as previously described. The rocking of this rod will now actuate the rod 74 to clutch up gear 42. This gear will now rotate at the same R. P. M. as gears 55, 56 and cam members 80 and 81 so that the cams 80, 81 will retain the position to which they have been moved laterally and consequently the shaft C7 will be held in its rocked position.

Gear 55, (Fig. 36), now causes rotation of gear 71 and shaft 72. Said shaft (Figs. 16 and 19) carries one member 630 of a Geneva motion element, the other member 631 of which is fixed with respect to a gear 632. The latter is connected through gears 633, 634 to a gear 635 fixed on shaft 636. Said shaft has slidably non-rotatably mounted thereon, a double clutch member 637, shown here as coupled to a gear 638 loose on the shaft. The said gear will thus be rotated and will transmit its motion to a gear 639 fixed on a sleeve 640 loose on shaft 392. Also fixed on sleeve 640 is a disc 641, (Fig. 22), having radially extending teeth 642 and laterally extending pins 643. As the disc 130

641 now rotates counter-clockwise, it will turn a lever arm 644 clockwise until it passes over pin 643 and drops back. Another lever arm 645 will be similarly rotated until it drops back over the tooth 642. A lever arm 644, loose on shaft 644a is normally held against the tension of a spring 644b. When the machine starts its total operations, the disc 641 will be rotated. In the present instance the disc will turn two steps during the total operations, representing the two machine cycles used for each total struck. The first of these steps carries the pin 643 out from under the lever 644, allowing spring 644b to raise its rear end. A lever 665 fixed on shaft 644a has a pin 666 resting on the top of arm 644 and will thus be actuated to rock said shaft, raising a link 646 on a lever 667 also fixed on the shaft. The raising of this link against the action of a spring 668, (Fig. 52), will interpose a stop 647 across the rear end of the total release key 648 which, as will hereinafter be explained, is adapted to restore to normal, the parts that have been set for taking a total. Thus, when the total operation has commenced, the total release key cannot be operated. During the second cycle, after the total has been struck, the second step of disc 641 rocks the arm 644 and permits the spring 668 to restore the parts. The first step of disc 641 is ineffective as to the arm 645. But near the end of the second step, the arm is turned and then released. This turning pulls down a link 649 connected to the latches 606 and 608, and releases the total key and the start key, allowing the total-control parts to assume normal positions, and causing the machine to stop.

During this total-taking, other operations are also taking place. For instance when the shaft C7 is rocked, it will actuate a lever 650, (Figs. 41, 42), to reset the finder in a manner described in connection with the finder. Also, a lever 651 (Fig. 54), is turned by rod C7. The first part of this motion tensions a spring 652 connected to lever 651 and a link 653 and tends to move said link to the right. A second link 654 is, at this time moved to the right. The latter link has a pin and slot connection with a spring-pressed latch 655 (see also Fig. 76) which normally rests on the top of bars 656, 657 and holds them in a depressed position. The bar 656 is connected to another bar 658 by a strip 658a, (Fig. 53), so that the latter bar is also normally held depressed.

After the lost motion in link 654 has been taken up, the latch 655 will be moved to the position of Fig. 76, releasing the bars 656, 657 and 658. The toggle 660 which has a fixed pivot at 661 with latch 655, and which is also connected at 662 to bar 658, will now straighten out under pressure of spring 652 and raise the bars 656, 657 and 658. This, in turn, will raise the racks 504, 505, 506

and 507 one tooth space before the accumulator wheels are brought into mesh therewith to control the printing of the total. The rocking of rod C7 also causes the card at the reading station to be held for a new reading after the total operations as previously described.

The selection and actuation of the accumulator from which the total is to be printed is as follows: When the start key is pressed for totaling, and gears 42 and 56, (Fig. 36), are brought into operation, the cam 680, (Figs. 11 and 62), will press the follower lever 681 fixed on shaft 326 outwardly. At the same time, gear 56, (Figs. 36 and 40), is through chain of gears 73, turning the shaft 682, on which is fixed a cam 683 (see also Fig. 41). A follower lever 684 is actuated to raise link 685. This through lever 686 fixed on shaft 326 helps to move follower lever 681 (Fig. 11) outwardly. When the low portion of cam 680 now reaches the follower 681, the latter cannot move back as the follower 684 (Fig. 41) is still on the high portion of cam 683 which rotates much slower than cam 680. The follower 681 is thus bridged across the low portion of cam 681 and is again received by the high portion. About the time the low portion of cam 680 again reaches the follower (Fig. 62), the follower 684 will ride off from the high portion of its cam. The follower 681 may now ride down to the low portion of cam 680. This will rock shaft 326 clockwise as viewed in Fig. 62.

Referring now to Fig. 64, when shaft 326 is rocked counter-clockwise, the layer 686 will depress the cam bar 528 to hold the accumulators in their present position out of mesh with their racks. When shaft 326 is again permitted to rock clockwise, the cam bar 528 is raised to the position of Fig. 64, so that any accumulators having been selected may be brought into operation. The turning of shaft 682, Fig. 41, will also through a cam 687, rock a lever 688 to raise a link 689 which is shown in Fig. 18, which is a view taken from the opposite direction, of the upper portion of the machine, will rock bell crank 690 clockwise. This will, through link 691 and lever 692, rock the shaft 693 clockwise. Turning to Fig. 24, which is a view from the opposite side to that shown in Fig. 18, the shaft 693 is rocked counter-clockwise. This will turn the plates 694, 695, (see also Fig. 71), in a similar direction so as to cooperate with shoulders 696, 697 on the type bars 294 so that when they are released to rise on the selecting stroke, they will be stopped at their zero position. The type restoring bar 298 is at this time raised and this releases a lever 698 to which is attached a link 699 running downwardly into Fig. 54 and connected to a link 700 fixed on shaft 701. Also fixed on the said shaft are levers 702, engaging the top of pins 703 fixed to links 704, 705, 706, and 707,

(see also Fig. 79). These link are attached to lever 704a, 705a, 706a and 707a, fixed on shaft 704b, 705b, 706b and 707b. These shafts as shown in Fig. 52 have springs 708 tending to rotate them in a clockwise direction as viewed in Figs. 54 and 79. Thus when the type restoring bar 298 releases lever 698, these springs will rock said shafts variable distances, depending upon the positions of notched discs 709, 710 (Fig. 80) which are adapted to stop levers 711 and 712 at various depths.

In Fig. 80 the parts are shown in an operative position; the levers 711 and 712 having moved as far as the discs have permitted. In consequence, the links 704 and 707 have been correspondingly raised, and have rocked the shafts 715, 716. As seen in Fig. 80a these shafts operate levers 717 and 718. Lever 717 is connected by a link 719 to a stepped lever 720, while lever 718 is connected directly to a stepped lever 721. These stepped levers have thus turned clockwise to present predetermined steps to the arms 722 of the accumulator selector combs 723, 724, 725, 726. The combs when released by the type bar restoring member 298 will rise under spring pressure as in the case of the type bars. The distances that they rise will be controlled by the stepped levers. The stepped lever 727 having no notched control disc similar to discs 709, 710, is free to turn its full distance and thus permit its comb 724 to rise its full distance. The comb 725 is also free to rise its full distance. It may be stated here that a disc similar to discs 709, 710, properly notched may be provided to control stepped lever 727, and comb 724 should additional accumulators be applied to the machine, to afford a greater member of comb notch combinations for accumulator selections. The combs having risen as in Fig. 80a, one of the several bars 536, i. e., 536g, finding openings 728 in all of the combs, will enter when released. The bar 536 as described in connection with Fig. 72 determines whether that particular accumulator shall mesh.

Referring now to the particular total which we have been describing, the discs 709 and 710 are in the position of Fig. 79; full depth notches being presented to the levers 711 and 712. This will permit all of the combs 723, etc., to rise their full distances. In this case the bar 536j will operate, permitting the accumulator A10 (Fig. 63) to enmesh, to control the heights to which the type bars shall rise during the next machine cycle to print the total. The cam 687 (Fig. 41) which prevents the type from rising all the way during the accumulator selecting cycle, will now have released the type bars of printing operations.

To stop the machine the stop key 997 (Figs 20 and 21) is pressed. This will, through a bell crank 997a depress a link 997b,

Fig. 16. This will rock a bell crank 997c connected by link 997d to a lever 997e fixed on a rod 997f (see also Figs. 38 and 43). Also fixed on said rod is a lever 997g which, acting on a pin the latch 585, will actuate said latch to release the lever 580 on shaft C4. As we have seen this will permit the machine to stop excepting for the latch 606, Fig. 20, which cooperates with the shoulders 607 on the start key. At the same time that the stop key is pressed, however, it will actuate a bell crank 997h to depress the link 997i connected to the latch 606. This will release the start key so that it may return under tension of its spring to stopped position. It will be noted here that the stopping of the machine under such conditions will not affect the total key 601 nor the set up controlled thereby, so that if the machine was in a totaling operation when stopped, it will when restarted, continue with said operation.

In Fig. 20 I have shown two latches 990 adapted to cooperate with pins 991 to lock the total and total release keys against operation. When the start key is pressed, pins 992 on link 562 will permit the springs 993 to move the latches into locking position. This will prevent operation of the total and total release keys while the start key is in running position.

In Fig. 88, I have shown the accumulator A4 as adapted to be selected by a comb bar 979. This accumulator may be independent of the selector combs that select the other accumulators. The comb 979 may normally rise its full distance when released by restoring bar 298, but when the lever 981 is depressed the bar 980 will be thrust into the path of the stop 982. This will then stop the bar 979 with the notch 983 in position to select the accumulator. The other accumulators may be locked out by raising the plate 912 (Fig. 15). Now, when the pins take readings from the particular part of the card being used, the data will be run into this accumulator, and when a total is struck, it will be from this accumulator.

Automatic total taking

We have shown how a total may be taken by manual initiation after the machine is stopped by a change of classification in the cards. Means for doing this automatically will now be described.

Depression of the auto control lever 1000 to the position shown in Figs. 20 and 21 will depress one of the links similar to link 611. The particular link being designated 611a in Fig. 16. This link is connected to a bell crank 1001 to actuate a link 1002 attached to a lever 1003 fixed on the shaft C1. The shaft then is rocked counter-clockwise, moving a lever 1004 fixed thereon from the dotted line position of Fig. 47 to the full line position. This will move the pin 1005 on

said lever toward the right in the slot in a link 1006, so that the latter may subsequently be moved to the right. Attached to this link is a bell crank 1007 engaging the tops 5 of a pair of rocker bars 1008, 1009. These bars are pivoted at 1010 (see also Fig. 38). The rocker bar 1009 normally tends to rotate counter-clockwise as viewed in Fig. 38 and is locked in a horizontal position by a latch 1011. A similar latch 1012, Fig. 45, is adapted to lock the bar 1008 in a similar position, but is normally unlatched therefrom. Riding over the top of the rocker bar 1009 are 2 actuating levers 1013, 1014, 10 the lever 1013 also rides on the rocker bar 1008 which is shown in Fig. 38 as shorter than the bar 1009 and therefore does not reach under the lever 1014. Presuming the start key to have been pressed after the actuation of the automatic lever, the machine 15 will start operation as heretofore set forth. Now when a change in classification occurs, causing clockwise movement of lever 587, Fig. 43, the latch 582 will be tripped. Also 20 a lever 1015 is rocked counter-clockwise. This lever is fixed on a rod 1016 on which is also fixed the latch 1011 so that the latch will release the rocker bar 1009. These bars will now rock counter-clockwise, rocking the bell 25 crank 1010, Fig. 47, counter-clockwise to the position shown in Fig. 44. The dropping of these bars will also permit the lever 1013 to drop to the position of Fig. 46 cooperating with a pin 1017 on lever 1018 fixed on the 30 shaft C3. The lever 1014 at the same time dropping to the pin 1019 fixed on the lever 1020. When this happens the levers 1013 and 1014 are in the withdrawn position of Fig. 45. Now when the stud 1021 carried 35 by the worm wheel 29 engages the cam lever 1022, it will rock a lever 1023 fixed on the same sleeve therewith in a clockwise direction moving the levers 1013 and 1014 to the left. This will then rock the lever 1018 40 to the position of Fig. 46 to turn the rod C3 in a clockwise direction. This has been pointed out in connection with the operation of the total lever and effects a set up for the taking of a total. The lever 1014 in 45 the meantime is riding on the pin 1019. Now when the stud 1021 releases the cam 1022, the spring 1024 will return the levers toward the right and the lever 1014 will ride off from the pin 1019. The lever 1018 is 50 locked in its set position as previously described. Lever 1014 will now cooperate with a pin 1025 on a lever 1026 fixed on the shaft C4. When the stud 1021 again moves the parts to the left, the shaft C4 will be 55 rocked in a clockwise direction which is the equivalent of pressing the start key. This will cause the machine to commence a totaling series of operations in the manner heretofore set forth. In these operations we 60 have seen that the shaft C6 is rocked clock- wise. This shaft carries a cam 1027, Fig. 45, which normally holds a latch 1028 to the left. This cam is now moved to release said latch which is drawn by its spring 1029 against the rocker bar 1009. We have also 65 seen that at the commencement of the totaling operations the shaft C7 rocks counter-clockwise. This will, through a lever 1030, pull the link 1031 toward the right as viewed in Fig. 47 and rock the bell crank 1007 clockwise restoring the rocker bars 1008 and 1009 to normal position, lifting the levers 1013 and 1014 back to their upper positions. The latch 1028, Fig. 45, having a shoulder 1032 will now lock the bar 1009 in its restored 70 position. The machine will now take the total shown in Fig. 6, that is, it will print one of the lines 730. At the end of this operation the disc 641, Fig. 21, will release the total and start keys as has been set forth. 75 During the foregoing operations when the shaft C7 is rocked counter-clockwise, it will through a lever 87, connected by a link 1033 (see also Figs. 37 and 41), to a latch 1034 pivoted on the depending link 854, move 80 said latch into cooperation with a pin on the bell crank 593. While the total is being taken the link 854 as we have seen is moving up and down. This will then rock the bell crank 593 counter-clockwise once for 85 each stroke and as we have seen, will constantly lift the latch 582 which as we have seen will at this time be without effect. When the disc 641, Fig. 21, causes the total and start keys to be released, the total key 90 will move back to normal position, but the start key will be held by the pin 583, Fig. 43, as the latch 582 will at this moment be in latching position. The return of the shaft C3, Fig. 39, will then rock the double latch 95 596 back from the dotted line position to the full line position. The other parts being in the positon shown in Fig. 39 at this time. 100 The shaft C6 being released will, under tension of its spring 69, (Fig. 41), rock counter-clockwise to allow the clutch to engage and stop members 57 and 59. The cam 1027 fixed to shaft C6 will return to its normal position as shown in Fig. 45. Rocker bar 1009 is at 105 110 this time held in a horizontal position by latch 1011. The latch 1034 (Figs. 41 and 43) descending at this time will, as has been described, rock latch 582 to allow shaft C4 to return to 115 normal position, and also turn latch 1011 to allow rocker bar 1009 to tilt. 120 Referring to Fig. 49 a link 1034a spring-connected to arm 1020 loose on shaft C3 is adapted by connection to lever 1035 to hold 125 arm 1020 in the position shown. 125 The shaft C7 has fixed to it a gear 1036 which, due to the previous clockwise motion of said shaft will turn a sector 1037 loose on shaft C6. As seen in Fig. 44 an arm 1038 130

integral with sector 1037 will, through link 1039 also fixed to lever 1035, turn said lever from the position of Fig. 44 to that of Fig. 49. Latch 1012, will through link 1040, be permitted to turn counter-clockwise, under tension of its spring to engage rocker-arm 1008 and hold it in a horizontal position.

As has been shown the tilting of rocker arm 1009 will allow actuating lever 1014 to turn counter-clockwise about its center, and as arm 1020 carrying pin 1019 is held to the left, as in Fig. 46, said actuating lever when in its right position will fall on pin 1025 in lever 1026. When actuating lever 1014 is next moved to the left it will through pin 1025 turn shaft C4 clockwise to resume operation of the machine. Meanwhile shaft C7 has returned to its normal position of Fig. 44.

In Figs. 44 and 47, pin 77 and gear 31 will through cam 76 and link 75 having a lateral projection 1041, rock bell crank 1007 to restore rocker-arm 1009 to its horizontal position. The machine is now operating as when the start key was first pressed, and is accumulating data from the cards. Should a disagreement now occur in the classification in fields 16 or 17 on cards 10 or 18, the finder will cause link 589 (Fig. 41) to be depressed. A pin 590 on said link will, as has been shown, turn lever 587 clockwise to unlatch shaft C4 and initiate the aforementioned automatic totaling operations.

The lower edge of link 589 is adapted to engage a pin 1042 in a latch-lever 1043 pivoted on a bracket 1044. A shoulder on latch-lever 1043 is adapted, normally, to engage a pin in arm 1045 to hold it in the position shown in Fig. 41 against tension of the spring 1046.

A second latch 1047 pivoted on an arm 1048 fixed on shaft C7 is spring-pressed against a pin 1049 in arm 1045.

Thus, when link 589 engages pin 1042, turning latch-lever 1043 clockwise, the arm 1045 will be released and spring 1046 will turn shaft C5 counter-clockwise as shown in Fig. 50.

Referring now to Figs. 16 and 21, a vertical rod 1050 has fixed to it a forked arm 1051 adapted through pin 1052 in rod 1053 to move said rod horizontally. Fixed to rod 1053 is a forked arm 1054 (see also Fig. 20) normally adapted to hold clutch member 637 in engagement with gear 638 as shown in Fig. 16.

Thus, counter-clockwise motion of shaft C5 will through arm 1055 and link 1056, pin and slot connected to an arm 1057 on rod 1050, turn said rod to move rod 1053 to the right as viewed in Fig. 16. Clutch member 637 keyed to shaft 636 will now engage and drive gear 1058 which through gear 392a is adapted to turn cams and discs which control the mechanisms for printing totals on record sheets R1 and R2. A member 1059 fixed to gear 1058 having suitable notches is adapted to be engaged by a roller on spring-pressed detent

arm 1060 to centralize the discs as they are turned step by step through the Geneva stop motion heretofore described.

When the discs have made a complete revolution and a line 731 has been printed on record sheet R2, together with line 730a on record sheet R1, the machine will as heretofore explained automatically reset and continue accumulating data from the cards.

As has been shown during totaling, the shaft C7 is in a counter-clockwise position holding lever 1048 likewise. This allows latch 1047 to drop on pin 1049 in latch-lever 1043 and on the resetting of shaft C7, a shoulder on latch 1047 will engage the pin in arm 1045 turning the shaft C5 clockwise and permitting the shoulder on latch-lever 1043 to engage and hold it in this position through arm 1045.

Referring now to Figs. 79 and 80, the selector combs 723, 724, 725 and 726 are adapted, during totaling, to be positioned by stepped levers 720, 721 and 727. These levers, as has been shown, are controlled by discs 709, 710. During the taking of a total to be printed on record sheets R1 and R2, the discs together with others for controlling the shifting of the carriage, raising the platen, etc., as heretofore described, are suited to advance step by step, permitting through aforementioned mechanism, the levers 720, 721 and 727 to position themselves so that they will stop the selector combs at various positions.

The discs 709 and 710 are so cut that the selector combs controlled thereby are given a predetermined combination of positions which are adapted to select the accumulators in the sequence in which the information contained therein is to be printed on record sheets R1 and R2.

In Fig. 80 are shown the various controlling elements in operative position. The combination of positions on the selector combs is such as to select the accumulator A7, through bail 536g, for printing in column AA7 on record sheet R2, Fig. 5.

In Fig. 16 are shown two sets of discs 1088 and 1089 controlled through gears 1090 and 1091 respectively. These discs may be cut in a similar manner to those described to control mechanism for printing totals on record sheets other than those shown.

These sets of discs may be brought into operation automatically as those heretofore described, but in the drawings are shown as being manually controlled. A driving member 1092 is normally positioned midway between the clutch members on disc sets 1088 and 1089. A forked arm 1093 similar to 1054 is fixed to a sleeve 1094 adapted to slide horizontally along shaft 1053.

In Fig. 21 a hand lever 1095 may be moved down to depress a link 1096 fastened to a bell crank 1097. Clockwise rotation of said

bell crank will through pin and slot connection slide sleeve 1094 to the left engaging the driving member of the clutch with disc sets 1088. Similarly, an upward movement of lever 1095 will by moving sleeve 1094 to the left, engage discs 1089.

5 A vertical arm 1098 having a pin 1098a is pivoted at its lower end and through pin and slot connection is adapted to slide shaft 1053 horizontally.

10 The clockwise or counter-clockwise motion of bell crank 1097 will cause pin 1098a to follow in slot 1099, turning arm 1098 clockwise, which will centralize clutch member 637 between gears 638 and 1058 maintaining their respective sets of discs inoperative. During the taking of a total, a cam 291 is adapted to rock lever 289 to lock the combination combs 233 against operation as heretofore shown.

15 20 A lever 1061 will, through the rocking of total shaft C7, rock member 1062 into the path of roller 290 and hold lever 289 in operative position while the totaling mechanism is functioning.

25 Referring to Fig. 6, the first total to be printed in column B10 is accompanied by the printing of data in columns 746, 745 and 743. Subsequent printing in columns 745 and 746 is suppressed until the line 730a is 30 printed.

The mechanism for suppressing this information will now be described. In Figs. 53, 65, 71 and 92, a rod 1063, extending across the type bars controlling the printing in the columns 743, 745 and 746 in question and also columns 742 and 744, is adapted, when any of these type bars rises to present a significant figure on the printing line, to be rocked by a cam surface 1064 on said type bars about its axis 1065 in a counter-clockwise direction. Similarly the rising of the type bar controlling column 741 will rock on arm 1066. Bails 1067 and 1068 are normally held in inoperative position by latches 1069 and 1070 respectively. Pins in levers 1071 will, when said levers are rocked counter-clockwise due to the rising of the type bars, unlatch bails 1067 and 1068 so that upon restoration of said type bars the bails will drop into notches 50 1072 and prevent subsequent rising of the type bars.

55 As has been explained heretofore the classification contained on these type bars is run into accumulators A5 and A10—accumulator A5 taking only year and kind designations to be printed in columns 745 and 746 of sheet R1 and on R2.

60 When an age total is to be taken the first line 730 on sheet R1 is to be printed from accumulator A10. Referring to Figs. 92 and 53 the straightening of toggle 660 will through lever 1073 raise link 1074 to rock rod 1075 counter-clockwise. An arm 1076 fixed to said rod will through a pin in bail 1067 disengage said bail from the type bars

to allow them to rise in mesh with the accumulator wheels and print the information contained thereon. An arm 1076 on rod 1075 will release the type bar to print an asterisk in column 741 of sheet R1.

70 A latch 1077 is normally spring-held to the left of pin 1078 in bail 1068. A pin 1079 in bail 1067 will engage latch 1077 which will through pin 1078 withdraw bail 1068 allowing the year and kind type bars to rise. The latch 1077 is adapted to swing to the right of pin 1078 allowing bail 1068 to again suppress the type bars when they have descended after printing line 730 on sheet R1.

75 80 Bail 1067 is held by latch 1069 to allow the age type bars to take another reading. For subsequent age totals to be printed on sheet R1 the latch 1077 being positioned to the right of pin 1078 will not unlatch type bars to print in columns 745 and 746.

85 When a kind total is taken the clockwise rotation of shaft 926 will through link 1080 and arm 1081 rock rod 1082 similarly. An arm 1083 fixed to said rod will through pin and slot connection with bail 1068 disengage it from the type bars which will now rise in mesh with the accumulator A5 to print line 90 730a on R1.

95 A latch 1084 on rod 1085 will engage pin 1078 in bail 1068 at this time and hold said bail inoperative until the totaling mechanism has functioned to print a line on sheet R2, Fig. 5. This latching up of bail 1068 will allow latch 1077 to swing to the left of pin 1078. At the end of totaling, a link 1086 connected to lever 651 on shaft C7 will 100 through arm 1087 turn rod 1085 to unlatch bail 1068 to be held by its other latch 1070.

Subtracting

105 It is, of course, understood that subtracting in many adding machines is accomplished not by turning the accumulator wheels in the reverse direction, but by turning them in the usual direction and instead of running the number to be subtracted into the wheels, the complements of the digits are rolled into the wheels; the last carry being disposed of in a manner to be described. It has heretofore been pointed out that when a 110 digit is read from the card and the combination combs 233, 233a, Fig. 27, set up, the feeler bars 262 are released and one thereof advances if it finds an opening across the combination combs. This feeler bar in turn 115 controlling the position to which the type bar 294 may rise when released. It may now be stated that the combination combs when set up under control of a digit, present notches to permit the advance of two of the 120 feeler bars 262; one thereof being prevented from advancing by a lock-out plate 785, Figs. 15, 27 and 87. The said plate is provided with openings 786 through which the ends of the feeler bars 262 project. Some of 125 130

the feeler bars have notches 787 on their lower edges while others are provided with similar notches on the upper edges. Normally the plate 785 is in its lower position, locking all of the feeler bars having notches on the upper edges against operation. The feeler bars having the notches on the lower edges are then free to operate. These latter bars are then operating in normal accumulating operations and may be termed the positive feeler bars. When a number is to be subtracted from the accumulators the plate 785 is raised and the positive feeler bars locked against operation, while the bars having notches on their upper edges, which bars may be termed the complementary bars are free to advance. The manner in which the plate 785 is raised is as follows: A card representing a minus item has printed in the column 445 the digit 7. This is read in the usual manner by the feeler pins which in turn control a pair of combination combs 233b. One of these combs is shown as having a pin 789 which when the comb is permitted to descend rocks a lever 790 fixed on a shaft 791 to rock the latter. Also fixed on said shaft are a pair of levers 792, 793 adapted to raise the plate 785 and a similar plate 785a. Thus when a minus card is presented at the sensing station the positive feeler bars are rendered inoperative and the complementary feeler bars are unlocked for operation. Now when the type bars are released they are raised to a position to print the complements of the numbers taken from the card or when printing is not effected at this stage these complements will simply be run into the accumulator. In this case it may be stated that the pair of combination combs 233b may be controlled by a 7 or a blank. The bar 447, Fig. 85a, is adapted to advance and through projection 449 actuate the lever 450 to suppress printing as has been explained. The combination comb 233b, other than the one which carries the pin 789, has fixed thereto a depending link 794, Figs. 15 and 63, which at its lower end near the bottom of Fig. 63 is attached to a latch 795 shown in its normal unlatching position. Normally, a lever 796 having a pin 797 and fixed on a shaft 798 is adapted to oscillate. A lever 799 connected to a link 900 is in turn attached to lever 901 fixed on shaft 326, the operation of which has heretofore been described. When this comb descends under control of a minus card, the latch 795 is thus brought into cooperation with pin 797 so that on the next clockwise movement of shaft 798, said latch is moved to the right against the action of spring 902 and through lever 903 will rock a shaft 904. Fixed to this shaft is bail 905 as seen in Fig. 65. The movement of this bail moves a spring-pressed stop 906 to the right permitting the racks 506 and 507 to drop relatively to the type bars a half

tooth space. This happens before the type bars rise. As the type bars rise carrying the rack 505 away from the bar 658, this rack will also drop a half tooth space with respect to the type bar. Now when the type bar is stopped by the complementary feeler bars, it will be stopped at an intermediate position, or in other words, a half stop above its normal or positive position and will thus present at printing position the complement of the digit taken from the card. The racks 505, 506, 507 are now in proper position to receive the accumulator wheels which are now brought into mesh. Now when the type bars descend, the complementary number is rolled into the accumulators. Near the end of the restoring movement, the racks strike the bars 656, 657 and 658 and will stop while the type bar continues for a short distance carrying the stop member 906 clear of the racks and permitting it to be returned to normal position by its spring.

Referring to Fig. 86, the type bar is provided with a pin 907 which when the last type, which is the complementary zero, is in printing position, will engage a lever 908 and raise the member 347 to the heretofore described non-printing position.

In Figs. 85, 85a, is shown a lever 909 fixed on a shaft 910 on which is also fixed a lever 911 adapted to raise a plate 912, similar to the plate 785 which has been described. Movement of lever 909 to rock shaft 910 clockwise will raise the plate 912 to lock the bar 447 against operation. This may be used in certain operations of the machine when it is not desired to suppress printing at this particular point.

Paper insert control

In Figs. 94 and 94a means are shown whereby a sheet of paper is being inserted in the machine a lever may be actuated to quickly draw the paper into the machine to a position placing a predetermined line in readiness to receive the impression from the type. This mechanism will effect a set up such that when the sheet in the machine is removed and reversed and re-inserted for printing on the opposite side, operation of the aforesaid lever will now draw the paper into position presenting a line nearer the top of the page in readiness to receive the type impressions. The shaft 1100 of the upper paper platen has fixed thereon a pinion 1101 meshing with a gear 1102, loose on a shaft 1103, carried by bracket 369. A lever 1104 having an actuating pawl 1105 cooperating with said gear will, when turned in the clockwise direction, cause a quick rotation of the paper platen to draw the paper in in the usual manner. After the lever has been actuated a short distance it will engage a projection 1109 to stop the lever 1104. When the operating lever is now returned to nor-

mal position, the pins 1108 thereon will engage one of the stops 1110 which will have been raised by a pin 1111 on the wheel 1107 as in Fig. 94a. This will stop the lever forward of its normal stopping position, so that when it is again pulled forward its full stroke, this movement will be less than previously. Thus when a sheet having a heading is inserted the first printing line presented will be below said heading and when the sheet is reversed, presenting the opposite side having no heading, the first printing line presented will be nearer the top of the sheet. A resiliently actuated detent 1112 for cooperating with notches in a disc 1113 fixed with respect to wheel 1107 will tend to hold said wheel in the position to which it is moved by pawl 1105. On the second of these two strokes of lever 1104, the pin 1111, along with the wheel 1107, will be turned another notch, so that this time the operating lever may swing back its full stroke, as the stop 1110 will have dropped.

25 *Line printing limit control*

In Figs. 95 and 97, I have shown means adapted to control the number of lines that may be printed on a sheet of paper. This means comprises an adjustable device which 30 may be set to stop the machine as well as to ring a bell after a certain number of lines have been printed on the report sheet. A bell 1114 having graduations marked thereon, each graduation mark representing one 35 line on the report sheet, is mounted for rotation relatively to a ratchet 1115. A zero position index 1116 may be marked on the ratchet and the bell rotated so that the number of lines to be printed as represented by 40 the graduations thereon is set adjacent said index. At each spacing operation the shaft 451 is normally in the position shown in Fig. 95a and being connected by a link 1117 to a latch 1118 holds said latch in co-operation 45 with a pin 1119 on a lever 1120 fixed on shaft 1121. A shaft 310 oscillates once each machine cycle as heretofore set forth and will, through lever 1122, rock shaft 1121, move a bell crank 1123 to depress link 1124 and 50 actuate the spring-pressed pawl 1125 to click the ratchet 1115 one notch when it will be locked by the locking pawl 1126. After said ratchet has been clicked along as many times as 55 represented by the aforesaid set up, carrying the bell 1114 with it and also arm 1127, said arm will engage a by-pass 1128 on a lever 1129 turning the latter counter-clockwise, moving a member 1130 to the right, so that a pin thereon will engage the lever 1131 60 which supports the spring-pressed bell hammer. After the arm 1127 has passed over the by-pass 1128 to release it, its spring will return it to normal position. Just before this happens, however, the pin on member 1130 65 will ride past lever 1131 and release the latter

so that the bell will be sounded indicating to the operator that the line limit has been reached. The normal position of lever 1129 is shown in Fig. 95 holding a bell crank 1132 in depressed position. When lever 1129 is 70 actuated by arm 1127, it will release the said bell crank permitting the latter to be drawn by its spring to the position of Fig. 95a, positioning a pin 1133 in position to be engaged by the bell crank 1132 which is carried by 75 the stop key 997 to the right to bring the machine to a stop. A link 1124 is shown as connected to the lever 1123 by a pin and slot connection, the slot being in the link and being wider on one side than on the other. 80 Normally the pin is in the wide portion of the slot so that when the latch 1118 rocks lever 1123, a slight lost motion takes place before the ratchet 1115 is actuated, but when the arm 1127 engages lever 1129 and rocks 85 the same, a link 1134 will shift the link 1124, so that the pin in lever 1123 will now be in the narrow portion of the slot 1124; thus when the lever 1123 is given its next stroke it 90 will impart a greater movement to the ratchet 1115. This will insure the passage of the arm 1127 over the by-pass 1128 during the proper stroke. This automatic stop and alarm device may be rendered inoperative by depression of a lever 1135. The opposite 95 end of this lever carries cam surfaces 1136 and 1137 adapted to cooperate with pins 1138 in the pawls 1125, 1126, so that depression of said lever will cam the pawls out of engagement with the ratchet and hold them 100 disengaged. A pin 1139 fixed in the ratchet 1115 is adapted to engage a by-pass stop 1140. When the ratchet is disengaged as just set forth, it is actuated by the usual spring to bring it to a position where the pin 1139 will 105 strike said stop 1140, which will be its zero position. When the paper is being inserted and the arm 1104 is drawn forward, a depending extension 1141 thereon will engage a lever 742 and turn the same clockwise. 110 Said lever is fixed on a shaft 1143 on which is also fixed a lever 1144 having a pin and slot connection with link 1145. This link is connected to an arm 1146 of the lever 1135, so that the latter will be turned counter-clockwise when the paper is inserted. This 115 will cam out the pawls in the manner described and permit the parts to return to their normal position ready for operation in connection with printing on the report sheet 120 then inserted.

Operation of the machine

In Fig. 9, I have shown in diagrammatic form the manner in which the machine operates under control of a perforated card to distribute data from said card to the various accumulators, and upon presentation to the reading pins of a card of a different classification, printing the data contained in the ac- 120

cumulators in their proper columns on the report sheets.

In this diagram the field 13a on the card is inoperative, the pins controlled by said field being locked out as described. These pins if released would cause printing in the column 1147 on the report sheet R2. The field 14g is adapted to control the age accumulator A10 as indicated, the data in these columns is conveyed to said accumulator as heretofore described. The data in fields 14d and 14e representing the year and kind is also transmitted to the kind accumulator A5. Data in the field 1148 is adapted to be conveyed to the accumulator A4, but is in the present instance locked out. The data contained in field 1150 which comprises the amount of insurance is adapted to be conveyed to the accumulators A5, A10, and a selected one of the accumulators A1, A2, A3, A6, A7 and A8. The selection of the latter six accumulators is effected through the comb bars 723, 724, 725 and 726, the positions of which in turn are controlled in the following manner: The bar 723 being controlled through field 445, bar 724 being controlled by the right column of said field and bar 726 is controlled through the finder mechanism, which in turn is controlled through the fields 14d, 14e and 14g in the manner heretofore described. As shown at 1151, if the performances in field 445 represent a change or new card, the data on the card goes to the age and other accumulators as has been pointed out. If there is no change card accompanying a balance card, the data is carried to the kind accumulator. When a change occurs in the age group, the totaling operations will be initiated as has been set forth and the data in the age accumulator is printed in the columns B10, 743, 745 and 746 of the report sheet R1. Printing in the columns 745 and 746 is as we have seen suppressed on subsequent printing until the kind shall change. Upon a change in the kind group, the data in the accumulator A5 is distributed to columns B10, 745 and 746 on the report sheet R1 and then repeated on sheet R2 in columns AA5 and the year and kind columns after which the data in accumulators A1, A2, A3, A6, A7 and A8 is printed in the columns AA1, AA2, AA3, AA6, AA7 and AA8 respectively. The accumulators are cleared during these printing operations. When the accumulator A5 is cleared, its data is transferred to accumulator A9.

Timing diagram

Referring to the timing diagram shown in Fig. 98, the complete circumference of this diagram represents one complete cycle of operation of the machine. The data contained within the several concentric circles designated A, B, C and D, represent the operations of the machine during different cycles.

Thus, the operations designated in the circle A take place during a listing cycle; those in the upper half of circle B, during the half cycle used to set the machine up for totaling; those in the lower half of circle B, during the half cycle used to reset the machine for listing; those in circle C, during the cycle used for selecting the accumulator or accumulators from which a total is to be taken; and those in circle D, during a cycle used for printing a total.

The radial line designated "Machine Starts" represents the starting point of the machine. The other radial lines show in terms of degrees, the portion of a cycle within which the various operations take place.

The "machine starts" position is the point at which the machine clutch stops all operations and is therefore, the point from which the parts again start to move. This is an arbitrary point and is a convenient point at which to stop the machine because the card sensing pins, for instance, are in retracted or non-reading position. It is thus possible to remove a card from the reading position, when desirable, while the machine is at rest. When the machine stops many of the parts will be in the midst of their operating strokes and will stop moving at this point. When the machine is again started these parts resume their movements and complete their strokes.

To ascertain the timing of operations during a listing cycle, the datum in the circle A is read in a clockwise direction. Presuming the machine to be running, and commencing to read at the horizontal radial line at the left as an arbitrary starting point of a listing cycle, and which may be termed the 0° line, it will be seen that the accumulators immediately begin to be withdrawn from their actuating racks and that this withdrawal is completed at the end of 45° of the machine cycle. At the same time, the data-sensing pins are withdrawn from reading position, to permit a card to be fed to the reading station. Also, during this time, the feeler bars 262 move in (to the right) as viewed in Fig. 24. During the next 90 degrees the accumulator selector bars and the type bars take their readings from the feeler bars. Beginning at the same time and running through the same 90 degrees plus 15 degrees additional, the hammer reset bail 357 (Fig. 24), is withdrawn from engagement with the hammers so that the latter may operate when released.

As soon as the type bars have completed the taking of their reading the accumulators that have been selected drop into mesh with the rack teeth on the type bars, and the pawls 317 (Fig. 24), move into engagement with the type bars to prevent them from further rising when the feeler bars are withdrawn. These operations take 45 degrees. As soon as the hammer reset bail has been fully with-

drawn, the hammers are tripped to effect printing. During the next 45 degrees the feeler bars are withdrawn; the hammers are restored and the accumulator selectors are disengaged. After this, the selectors and the type bars are restored during approximately 90 degrees of a cycle, and the accumulators take their readings from the descending type bars in approximately 60 degrees, while the 5 combs 233 are restored in about 30 degrees, followed by the advancing of the data-sensing pins 181 in about 60 degrees. Following the operation of the accumulators and partly overlapping the restoration of the type and 10 selector bars, and the advancing of the pins is the operation of the finder, which continues to the end of the listing cycle. During the last 45 degrees of the cycle the combs 233 descend, and the pawls 317 disengage the type 15 bars.

It may be explained here that some of the operations performed during the latter part of the cycle are advanced operations associated with the next listing cycle. For instance, the advance of the pins through a 20 card, and the setting of the combs in accordance therewith will control the setting of the feeler bars as soon as the next listing cycle commences. Thus, the reading of a card takes 25 place during the latter part of a listing cycle, to control the operations of the machine during the subsequent cycle. This advance reading permits the finder to operate ahead of the operating cycle which it controls, and if the 30 card belongs to the same group as the last card, the machine is permitted to pass into another listing cycle to apply the data on the card to the accumulators. If the card is of a new group, however, then the finder activates mechanisms to prevent the machine from 35 repeating a listing cycle and causes it to commence totaling operations. The machine, without stopping, then performs the operations shown in the upper half of the circle 40 B. This prepares the machine for totaling. At the 180 degree line we pass from circle B to circle C, and continue to read in a clockwise direction through the 0 degree line back to the 180 degree line. These operations select the accumulator or accumulators that 45 are to control the total printing. We then pass from circle C to circle D on the 180 degree line, and read in a clockwise direction until the 180 degree line is again reached, and the operations listed will have produced 50 the total. We then go back to circle B on the 180 degree line and follow the lower half to the 0 degree line, and these operations cause the machine to be reset for listing. The machine then continues in circle A, beginning at 55 the 0 degree line. The operation will now be under control of the card whose readings caused the machine to take a total; said card having been held in position by stoppage of 60 the card feed when the listing cycle was sup-

pressed and resumed upon resumption of listing operations.

It will be recognized that this diagram does not show the timing of operation of all of the elements of the machine, but shows the operations of only the principal units; the timing of minor elements being readily ascertainable by their relation to these principal units. Nor are the timings shown in this diagram absolute, as it is possible to advance or retard many of the operations, or to overlap them in places without affecting the ultimate results.

What I claim is—

1. In a card-controlled tabulating machine, in combination, means for automatically successively feeding normally arranged cards therethrough, accumulating devices, and means for analyzing cards fed by said first named means for causing said accumulating devices to add and subtract items derived from the record cards.

2. In a card-controlled tabulating machine, in combination, a group of card-controlled accumulators for accumulating numbers represented upon a card, a group of accumulators for accumulating complements of the numbers represented upon the card, and a group of accumulators for accumulating both numbers and complements of numbers.

3. In a card-controlled tabulating machine, in combination, means for reading direct numbers represented by perforations upon a record card, a group of accumulators for accumulating direct numbers, a group of accumulators for accumulating complements of certain direct numbers and a group of accumulators for accumulating both direct numbers and complements of numbers.

4. In a card-controlled tabulating machine having accumulating devices, card-controlled means including perforation reading elements for entering complementary numbers into the accumulator when items are to be subtracted, means controlled by the same card-controlled elements for printing true numbers of complementary items.

5. A calculating machine having differentially movable record effecting devices, a wheel adapted to be differentially displaced thereby, said record effecting devices being arranged in two sets representing numbers and the complements thereof, means for variably displacing the record effecting elements to bring one or the other set of devices into position to produce records, said last mentioned means being ineffective to change the driving relations of the driven wheel and the record effecting devices.

6. In combination, an accumulator, a recording element positioned in accordance with the set-up of said accumulator and provided with two sets of record-effecting devices, either of which may be presented at the

recording position, one set to record numbers and the other complements of numbers, and means whereby either set of record-effecting devices may be rendered operative without changing the operative relationship between the accumulator and recording element.

7. In a tabulating machine having controlling combs, a plurality of groups of feeler pieces cooperating therewith, one group being adapted to pick off true numbers from said combs and the other to pick off complementary numbers therefrom.

8. In a tabulating machine having controlling combs, a plurality of groups of feeler pieces cooperating therewith, one group being adapted to pick off true numbers from said combs and the other to pick off complementary numbers therefrom, and card-controlled means for selecting the set of feeler pieces to be rendered operative.

9. A card-controlled machine comprising in combination, means for feeding cards through said machine in succession, means for counting the number of cards fed to the machine, means for totaling items represented upon said cards, and card-controlling means for suppressing the operation of one of said second and third named means.

10. A card-controlled tabulator, having means for accumulating data from cards, means for counting the cards, card-controlled means for selectively determining whether a passing card is to be counted or not, and card-controlled means for selectively determining whether an item is to be accumulated or not.

11. A card-controlled tabulating machine, including means for feeding cards through the machine, means for accumulating items from said cards, and means controlled by perforations upon a card or cards for selectively determining whether the datum perforated upon a card is to be accumulated or not.

12. A tabulating machine having reading devices and accumulator devices with provisions for receiving debit and credit entries from record cards, said machine also having provisions for entering balances derived from balance cards into said accumulators as debits and credits, and means operable by the presentation of a balance card to said reading devices for first introducing the balance entries to the accumulators, thereafter causing a record to be made of the new balance, and means for indicating when a balance is a new one.

13. A card-controlled machine comprising in combination, perforation-sensing elements, and means controlled by the presentation of a card for causing the taking of a total of data represented upon certain cards and means for indicating when the total is of data taken from more than one card.

14. A tabulating machine adapted to re-

ceive items from record cards and balance cards and to print a record of combined results therefrom in combination with means for recording a distinctive character upon the record upon the recording of a result which is different from the record shown upon a passing balance card.

15. A tabulating machine adapted to receive entries from both record cards and balance cards or from successive individual balance cards, means for printing new balance records representative of balances derived from the balance cards and changed or unchanged by items derived from the record cards or to print balances derived from the individual balance cards themselves, and means for printing a distinctive record when the printed balance record is different from the entry upon a balance card.

16. A card-controlled tabulating machine comprising in combination, means for accumulating positive and negative items, means controlled by a balance card for printing the algebraic sum of the balance represented upon the balance card and positive and negative items of other cards, and means for distinctively recording such printed sum when it is different from the balance represented upon the balance card.

17. A card-controlled tabulating machine, comprising in combination, means controlled by a succession of balance cards and interspersed item cards for accumulating items and balances, and means controlled by the presentation of immediately succeeding balance cards for printing balances and for suppressing accumulations.

18. A tabulating machine having provisions for receiving entries from record cards and balance cards and for accumulating results and printing the totals or new balances thereof, said machine also having provisions for reading successively presented balance cards and for printing the reading thereof and means for suppressing the operation of the accumulating devices when one balance card directly follows another balance card without the interposing of record cards.

19. A tabulating machine having a plurality of card-controlled type carriers, and means including a pin adapted to be projected into contact with the cards for permitting the displacement of said carriers upon the presence of a card in cooperation with said pin and suppressing said operation otherwise while permitting the machine to continue to run.

20. A tabulating machine having a plurality of type carriers having individual type and individual hammers for actuating the same, and means controlled by certain conditions in the passing cards for suppressing the hammer action to prevent the making of a report.

21. A card-controlled tabulating machine

- comprising in combination, perforation-sensing elements, record-producing means controlled by said elements, finder mechanism controlled by a plurality of card fields, 5 means controlled by said finder in response to a change in one of said fields for affecting the control of said record-producing means by said elements, and means controlled by said finder in response to a change in another 10 of said fields for differently affecting the control of said record-producing means by said elements.
22. A tabulating machine having provisions for making a plurality of forms of report and a card-controlled finder for initiating the making of certain forms of reports upon certain changes in classification perforations in the record cards, said finder also having provision controlled by other classification changes in the record cards for initiating the making of other forms of reports.
23. A tabulating machine having provisions for making at least two independent and different kinds of total-taking operations, a card-controlled finder controlled by classification changes in the perforated records, said finder having provisions for initiating one kind of total-taking operation upon a change in certain classifications and for 25 initiating a different kind of totaling operations upon a change in a different classification.
24. A tabulating machine having provisions for making reports in a plurality of forms and for effecting totaling operations of different kinds, and a card-controlled finder for initiating the making of one form of report and certain kinds of totaling operations upon the occurrence of certain classification changes in the record card, said finder also having provisions for initiating a different report making operation and a different set of totaling operations upon the occurrence of other classification changes in 45 the record cards.
25. A tabulating machine including accumulating means and printing means, said printing means including devices for printing a plurality of reports, total-taking mechanism effective to operate with both reports and in different ways thereon, a finder device controlled by classification changes in the perforated records, said finder having provisions for initiating the taking of totals on one report upon one change of classification, said finder also having provisions operable by a change of different classification for initiating the taking of grand totals of the totals previously taken on the first sheet, 55 printing said grand totals on the first report, repeating the printing of the grand total upon another report and thereafter distributing items entering said grand total upon the other report.
26. In a calculating machine, a type carrier
- provided with two sets of digits and record sensing means for controlling the setting of said carrier for selecting one of the digits from one of the sets for printing.
27. In a calculating machine, a type carrier having two sets of type, means for adjusting said carrier to position the type of either set for operation and means controlled by a perforated card for determining which set of type shall be selected for operation. 70
28. In a calculating machine, a type carrier having an ascending series of digits and a descending series of digits, means for selecting one or the other of said series and perforated card-controlled means for controlling said selecting means.
29. In a calculating machine, a type carrier having an ascending series of digits and a descending series of digits, means controlled by perforated cards for selecting one or the other of said series and means also controlled by perforated cards for selecting any one of the digits of the selected series. 85
30. In a calculating machine, a type carrier, a plurality of stops for determining the positioning of said carrier, means for selecting certain of said stops for operation and means for preventing operation of certain of the selected stops.
31. In a calculating machine, a type carrier, a plurality of stops for determining the setting of said carrier, means for selecting certain of said stops for operation and record controlled means for rendering certain of the selected stops inoperative. 95
32. In a calculating machine, a type carrier, means for operating said carrier, a plurality of sets of stops for determining the setting of said carrier, means for selecting a stop of each set for operation and means for suppressing the operation of the selected stops of one of the sets. 105
33. In a calculating machine, a type carrier, a plurality of sets of stops for determining the setting of said carrier, means for selecting a stop in each set for operation and means movable to one position for suppressing the operation of the stops of one set and to another position for suppressing operation of the stops of another set. 110
34. In a calculating machine, a type carrier having two sets of type, two sets of stops for controlling the setting of said carrier, means adapted when in one position to permit operation of one only of said sets of stops and when in another position to permit operation of the other set of stops only and means controlled by perforated cards for determining the position of said first named means. 115
35. In a calculating machine, a plurality of accumulator sets, a common actuator for said accumulator sets, means normally holding said sets out of cooperation with said actuator and adapted to selectively release one or more of said sets, a time actuated 125

- member normally holding all of said sets out of cooperation with said actuator and adapted to release all of said sets whereby the selected ones thereof may move into cooperation with said actuator and means for so moving said sets. 43. In an accounting machine, a plurality of accumulators for credit, debit and balance data, means for sensing numerical data on record cards, means controlled by record cards for determining whether the data shall be applied to the debit or credit accumulator and means for applying the data or their complements to the balance accumulator. 70
36. In an accounting machine, a movable type carrier provided with rack teeth on opposite edges thereof, a plurality of accumulator sets adapted to cooperate with said rack teeth, means for selecting certain sets of accumulators for cooperation with said rack teeth and means for causing the accumulators so selected to cooperate with said teeth. 44. In an accounting machine, a plurality of accumulators for credit, debit and balance data, means for sensing numerical data on record cards, means controlled by the record cards for selectively applying the data to the credit or debit accumulator and means controlled in accordance with such selection for applying the said data or their complements to the balance accumulator. 75
- 10 37. In a printing tabulator, a plurality of platens each of which is movable to operative position, an oscillating member for rotating whichever platen is in operative position, 20 and record-controlled means for moving the platens to operative and inoperative positions. 45. In an accounting machine, means for feeding balance cards and change cards, means for sensing the data contained on said cards, means for accumulating such data and means for causing a total to be taken whenever a balance card fed to the machine is followed by another balance card. 80
- 25 38. In a printing tabulator, a plurality of platens separately movable to printing position, means for rotating each of said platens when in printing position through angular movements of different values, and record-controlled means for moving the platens to operative and inoperative positions. 46. In an accounting machine, an accumulator, means for analyzing data cards and balance cards, means for entering data taken from the data cards into said accumulator, means controlled by the character of the data on said cards for causing data on a balance 90 card to be entered into the accumulator when the character of said datum is similar to that of data contained in the accumulator. 95
- 30 39. In a card-controlled accounting machine, means for accumulating data taken from control cards, means for printing data taken from control cards, and means for suppressing the printing of data under predetermined conditions governed by the cards. 47. In an accounting machine, an accumulator, record analyzing means adapted to sense numbers on record cards and to enter such numbers into said accumulator, and means controlled by cards for entering the complements of numbers contained thereon into the accumulator. 100 105
- 35 40. In a card-controlled accounting machine, means for accumulating data taken from control cards, means for printing data taken from control cards, means for suppressing the printing of data under predetermined conditions governed by the cards, means for feeding a report sheet and means for suppressing said feeding when the printing is suppressed. 48. In an accounting machine, an accumulator, means for analyzing records and for entering numbers or the complements of numbers contained on the records into said accumulator and means associated with said analyzing means for entering an additional unit into the accumulator when a complementary number is entered. 110
- 40 41. In an accounting machine, a plurality of accumulators, means for sensing numbers on record cards, means controlled by said sensing means for distributing such numbers to one of several of said accumulators and means controlled by the record card for determining whether such number or its complement shall be applied to another of said accumulators and means for making such entry. 49. In an accounting machine, an accumulator, record-sensing devices adapted to sense direct numbers and to enter such numbers as direct numbers or as complements into the accumulator, and means associated with said devices for automatically determining whether a true number or its complement shall be entered into the accumulator. 115 120
- 45 50. In an accounting machine, an accumulator, record controlled item receiving devices, intermediate devices for transmitting amounts from the item receiving devices into the accumulator as true numbers, means associated with the intermediate devices for converting true numbers received by the receiving devices into complementary numbers 130
- 50 55 60 65 70 75 80 85 90 95 100 105 110 115 120 125
42. In an accounting machine, a plurality of accumulators for credit, debit and balance data, means for sensing numerical data on record cards, means controlled by the record card which is being sensed for selectively applying such data to the credit or debit accumulator and means also controlled by the record card being sensed for selectively applying such datum or its complement to the balance accumulator. 130

and for adding such complementary numbers into the same accumulator.

51. In an accounting machine, an accumulator, item-entering devices, intermediate devices for causing an entered item to be added into the accumulator, translating devices associated with said intermediate devices for translating items into complements thereof and for causing such complements to be added into the accumulator and means automatically controlled by the operation of the machine for rendering the said translating devices operative or inoperative.

52. In an accounting machine, record controlled item-entering devices, an accumulator, intermediate devices for transmitting amounts from the item entering device into the accumulator, said intermediate devices comprising mechanism which receives a true number from the item entering devices and converts the true number into its complement and adds the complement of the true number into the accumulator automatically.

53. In an accounting machine, record sensing means, an accumulator translating means intermediate the sensing means and the accumulator for automatically converting a sensed direct number into its complement and for adding said complement into the accumulator.

54. In a perforated record controlled apparatus, a common accumulator adapted to receive items to be added thereon and from which amounts can be subtracted, sensing devices for sensing direct numbers upon a record card, converting devices disposed intermediate the sensing devices and the accumulator for converting direct numbers appearing upon record cards into complementary numbers and for entering the complementary numbers into the accumulator when the corresponding direct numbers are representative of items to be subtracted, said converting device being adapted also to enter numbers directly from the record cards into the accumulator without conversion when the direct numbers are to be added, and means for adding one to the last significant character in a complementary number when complements are added.

55. In a perforated record controlled apparatus, a common accumulator adapted to receive items to be added thereon and from which amounts can be subtracted, sensing devices for sensing direct numbers upon a record card, converting devices disposed intermediate the sensing devices and the accumulator for converting direct numbers appearing upon record cards into complementary numbers and for entering the complementary numbers into the accumulator when the corresponding direct numbers are representative of items to be subtracted, said converting device being adapted also to enter numbers directly from the record cards into

the accumulator without conversion when the direct numbers are to be added, and means controlled by a record card for adding one to the last significant character in a complementary number when complements are added.

56. In a perforated record controlled apparatus, a common accumulator adapted to receive items to be added thereon and from which amounts can be subtracted, sensing devices for sensing direct numbers upon a record card, converting devices disposed intermediate the sensing devices and the accumulator for converting direct numbers appearing upon a record into complementary numbers and for entering the complementary numbers into the accumulator when the corresponding direct numbers are representative of items to be subtracted, said converting devices being adapted to enter numbers directly from the record card into the accumulator without conversion when the direct numbers are to be added and printing devices controlled by the accumulator for printing the positive balance standing upon said accumulator.

57. In a perforated record controlled apparatus, a common accumulator adapted to receive items to be added thereon and from which amounts can be subtracted, sensing devices for sensing direct numbers upon a record card, converting devices disposed intermediate the sensing devices and the accumulator for converting direct numbers appearing upon records into complementary numbers and for entering the complementary numbers into the accumulator when the corresponding direct numbers are representative of items to be subtracted, said converting devices being controlled by the character of a designation in a given field on the record card.

58. In a perforated record controlled apparatus, a common accumulator adapted to receive items to be added thereon and from which amounts can be subtracted sensing devices for sensing direct numbers upon a record card, converting devices disposed intermediate the sensing devices and the accumulator for converting direct numbers appearing upon record cards into complementary numbers and for entering the complementary numbers into the accumulators when the corresponding direct numbers are representative of items to be subtracted said converting devices being adapted also to enter numbers directly from the record cards into the accumulator without conversion of the direct numbers to be added said sensing devices being adapted to sense said numbers from the same field on the record cards whether direct numbers or complementary numbers are to be added.

59. In a perforated record controlled apparatus, a common accumulator adapted to

receive items to be added thereon and from which amounts can be subtracted, sensing devices for sensing direct numbers upon a record card, converting devices disposed intermediate the sensing devices and the 5 accumulator for converting direct numbers appearing upon the record cards into complementary numbers and for entering the complementary numbers into the accumulator 10 when the corresponding direct numbers are representative of items to be subtracted, a supplementary accumulator adapted to receive all data entered as a true number into said first named accumulator and another 15 supplementary accumulator adapted to receive all data entered as a complementary number into said first named accumulator.

60. In a perforated record controlled apparatus, a common accumulator adapted to receive items to be added thereon and from which amounts can be subtracted, sensing devices for sensing direct numbers upon a record card, converting devices disposed intermediate the sensing devices and the 20 accumulator for converting direct numbers appearing upon the record cards into complementary numbers and for entering the complementary numbers into the accumulator when the corresponding direct numbers are 25 representative of items to be subtracted, a printing device arranged to list as direct numbers the entries into the accumulator and also to print as a direct number the total or balance standing in the accumulator.

61. In a perforated record controlled apparatus, a common accumulator adapted to receive items to be added thereon and from which amounts can be subtracted, sensing devices for sensing direct numbers upon a 30 record card, converting devices disposed intermediate the sensing devices and the accumulator for converting direct numbers appearing upon the record cards into complementary numbers and for entering the complementary numbers into the accumulator, a supplementary accumulator adapted to receive all data entered into said common accumulator as a true number, a second supplementary accumulator adapted to receive data entered into said common accumulator as a 35 complementary number, and means for adding an additional unit to all but one of the numbers entered into said second supplementary accumulator.

62. In a perforated record controlled apparatus, a common accumulator adapted to receive items to be added thereon and from which amounts can be subtracted, sensing devices for sensing direct numbers upon a record card, converting devices disposed intermediate the sensing devices and the ac- 40

cumulator for converting direct numbers appearing upon the record cards into complementary numbers and for entering the complementary numbers into the accumulator when the corresponding direct numbers 70 are representative of items to be subtracted, a supplementary accumulator adapted to receive amounts entered as true numbers into said common accumulator, a second supplementary accumulator adapted to receive amounts entered as complements into said common accumulator and means controlled by a record card for effecting the distribution of said numbers into said accumulators according to the class of the entry being made. 75

63. In a record controlled accounting machine, a plurality of accumulators, certain of said accumulators being adapted to receive positive amounts others thereof being adapted to receive negative amounts and another 80 being adapted to receive both positive and negative amounts, card controlled sensing devices adapted to sense the class of entry irrespective of its algebraic character and to secondarily sense the algebraic character of the 85 record and in accordance with such dual analysis control the distribution of the entries into a plurality of the accumulators.

64. In a perforated record controlled apparatus, a common accumulator adapted to receive items to be added thereon and from which amounts can be subtracted, sensing devices for sensing direct numbers upon a record card, converting devices disposed intermediate the sensing devices and the accumulator for converting direct numbers appearing upon record cards into complementary numbers and for entering the complementary numbers into the accumulator, a supplementary accumulator adapted to receive all data entered into said common accumulator as a true number, a second supplementary accumulator adapted to receive data entered into said common accumulator as a complementary number, and means for adding an additional unit to all but one of the numbers entered into said second supplementary accumulator. 95

65. In a perforated record controlled apparatus, a common accumulator adapted to receive items to be added thereon and from which amounts can be subtracted, sensing devices for sensing direct numbers upon a record card, converting devices disposed intermediate the sensing devices and the accumulator for converting direct numbers appearing upon record cards into complementary numbers and for entering the complementary numbers into the accumulator, a supplementary accumulator adapted to receive all data entered into said common accumulator as a true number, a second supplementary accumulator adapted to receive data entered into said common accumulator as a complementary number, means for adding an addi- 100

130

55 complement amount contained in said second named supplementary accumulator whereby the amount contained in the accumulator appears in printed form as a direct number.

62. In a perforated record controlled apparatus, a common accumulator adapted to receive items to be added thereon and from which amounts can be subtracted, sensing devices for sensing direct numbers upon a record card, converting devices disposed intermediate the sensing devices and the ac-

5 tional unit to all but one of the numbers entered into said second supplementary accumulator, and means controlled by a perforation in the record card for controlling said additional-one-entering mechanism.

10 66. In a perforated record controlled apparatus, a common accumulator adapted to receive items to be added thereon and from which amounts can be subtracted, sensing devices for sensing direct numbers upon a record card, converting devices for converting direct numbers appearing upon a card into complementary numbers and for entering the complementary numbers into the accumulator, means for clearing said accumulator, a supplementary accumulator and means for entering a number from the common accumulator into said supplementary accumulator when the common accumulator is 20 clear.

25 67. In a perforated record controlled apparatus, a balance accumulator adapted to receive positive and negative entries, a counter adapted to count all positive amounts entered into said accumulator and a second counter adapted to count all negative amounts entered into said accumulator.

30 68. In a perforated record controlled apparatus, a balance accumulator adapted to receive positive and negative entries, a counter adapted to count all positive amounts entered into said accumulator and a second counter adapted to count all negative amounts entered into said accumulator, and 35 means controlled by a record card for suppressing such counting.

40 69. Accounting apparatus including an accumulator and means for entering into said accumulator quantities representative of positive and negative amounts, said means including devices for entering positive amounts directly and for first converting negative amounts into complements and thereafter entering the complements into the 45 same accumulator, and means for operating said converting devices automatically by the operation of the machine.

50 70. The invention set forth in claim 69 in which perforated record reading instrumentalities are provided for controlling the entry of items into the accumulator and in which conversion into complements is effected intermediate the reading instrumentalities and the accumulator whereby direct positive or 55 negative numbers may be read from the perforated record.

60 71. An accounting machine including an accumulator, automatic record controlled means for entering amounts into the machine, means intermediate the entering means and said accumulator for converting said entered amounts into complements thereof, and means for entering into the accumulator said complements, the complements being based 65 upon nine in each order except the lowest

order containing a significant character and being based upon ten in such latter order.

72. An accounting machine including an accumulator, means for entering amounts into the machine, means intermediate the entering means and said accumulator for converting said entered amounts into complements thereof, means for entering into the accumulator said complements and means for automatically entering into said accumulator elusive ones for each complementary entry but one for the purpose described. 70 75

73. An accounting machine including an accumulator, record controlled devices for receiving amounts and for entering amounts into the machine as direct numbers, means for converting direct number amounts into complementary amounts, and means for entering said complementary amounts into the accumulator. 80

74. An accounting machine including an accumulator, record controlled means for entering amounts into the machine, and means intermediate the entering means and the accumulator for converting said amounts into complements thereof and for entering the same into the accumulator. 90

75. In a card controlled tabulating machine, in combination, means for automatically successively feeding record cards through the machine, means controlled by the cards thus fed for analyzing the cards for determining whether numbers represented in a field of a card shall be accumulated or their complements accumulated, and means for accumulating the numbers or their complements. 95 100

76. A tabulating machine comprising, in combination, record handling means, record analyzing means for analyzing true numbers upon the records, means including accumulating means and printing means controlled by said analyzing means for simultaneously adding complements and printing true numbers, and means to effect the printing of only the significant figures of the true numbers. 105 110

77. An accounting machine, including item entering devices, accumulating devices controlled thereby with provisions for accumulating complements of item entered by said devices, and printing means controlled by said accumulating devices with provisions for printing only the significant figures of a true number corresponding to the accumulated complements. 115 120

78. In an accounting machine, in combination, record sensing means for sensing number data upon record cards, a plurality of accumulators, means controlled by the sensing means for entering such a number into one of the accumulators and means also controlled by said sensing means for effecting the entry of such number or its complement into another of said accumulators. 125 130

79. In an accounting machine, the combination of an accumulator, means for sensing items upon balance cards and data cards, means controlled by the sensing means for 5 entering the items into the accumulator, a printing mechanism controlled by said accumulator and said sensing means, means controlled by said sensing means brought into action after the receipt of an item from 10 a balance card for causing the printing mechanism to print a total, means operative jointly upon the sensing of an item on a balance card and in response to a predetermined condition of the accumulator for causing 15 the printing mechanism to print an item taken from a balance card and means operating concurrently with said last mentioned operation for suppressing the entry of the balance card item into the accumulator by 20 said entering devices.
80. In an accounting machine, an accumulator, entry receiving devices adapted to receive representations of true numbers, means controlled by said devices for entering true 25 numbers into the accumulator, means controlled by said entry receiving devices for translating true numbers into complements and for entering said complements into the accumulator and means for deriving out of 30 the accumulator the amount contained therein.
81. In a perforated record controlled apparatus, a common accumulator adapted to receive items to be added thereon and from 35 which amounts may be subtracted, sensing devices for sensing direct numbers upon a record card, a translating unit including converting devices disposed intermediate the sensing devices and the accumulator for 40 converting direct numbers appearing upon cards into complementary numbers and for entering the complementary numbers into the accumulator when the corresponding direct numbers are representative of items to 45 be subtracted, said translating unit being adapted also to enter numbers directly from the record cards into the accumulator without conversion when the direct numbers are to be added.
- 50 82. A record card controlled accounting machine including accumulators, a printing mechanism and a balance card sensing mechanism, means controlled automatically by the operation of the machine upon said sensing mechanism sensing a balance card for alternatively causing said printing mechanism to directly print data derived from the balance card while suppressing the entry of data into the accumulators or in the event 55 of the sensed balance card data being correlated to data on additional cards, to cause said data to be entered from the balance card into the accumulator and to subsequently cause the printing mechanism to print a 60 new balance.

83. The invention set forth in claim 50 in which operating means is provided for automatically effecting the entry of a direct number or the complementary amount into the accumulator by the operation of the 70 machine.

84. The invention set forth in claim 50 in which the item entering devices comprise record sensing instrumentalities which co-operate with records to derive data therefrom. 75

85. The invention set forth in claim 50 in which means is provided operating automatically by the operation of the machine for automatically adding in the elusive one when required. 80

86. The invention set forth in claim 50 in which card controlled instrumentalities are provided for bringing about the automatic adding in the elusive one when required. 85

87. The invention set forth in claim 50 wherein a printing mechanism is provided controlled by the accumulator and in which means is provided for controlling the printing mechanism by the accumulator for printing the positive balance standing upon the accumulator. 90

88. The invention set forth in claim 50 in which the sensing means are provided for sensing records which are adapted to sense data representative of amounts to be added from the same card field and in which means is provided for identifying the character of such data by sensing a supplementary designation upon the record. 95

89. The invention set forth in claim 50 in which record sensing means is provided with supplementary designation sensing means for controlling the action or non action of the converting devices for the complements. 100

90. The invention set forth in claim 50 in which a plurality of supplemental accumulators are provided, which respectively 110 accumulate the totals of the positive amounts and the totals of the negative amounts which are entered into the common accumulator.

91. The invention set forth in claim 50 in which a supplemental accumulator is provided which receives complementary amounts only from said converting devices. 115

92. The invention set forth in claim 50 in which a printing device is provided for listing as direct numbers the entries into the accumulator and also for printing as a direct number the total or balance standing upon the accumulator. 120

93. The invention set forth in claim 50 in which a supplemental accumulator is provided which receives complementary amounts only from said converting devices, in combination with a printing device controlled by said accumulator for printing the 125 130

complement of the complementary amount standing upon said accumulator whereby the amount standing upon said supplemental accumulator appears in printed form as a direct number.

94. The invention according to claim 50 wherein a plurality of accumulators are provided, certain ones being for positive amounts, others for negative amounts and a common accumulator being adapted to receive both positive and negative amounts, in combination with card controlled devices for selectively effecting distribution of an entry into said accumulators both according to the algebraic character of the entry and to the class of entry to be made.

95. The invention according to claim 50 in which a supplemental accumulator is provided for receiving direct true members and in which a common printing mechanism is provided which under the control of said accumulator prints direct numbers of direct amounts standing thereon and which under the control of an accumulator receiving complementary amounts prints direct numbers of complementary amounts.

96. The invention according to claim 50 in which an elusive one entering mechanism is provided with means for operating the same automatically by the operation of the machine, with provisions to omit the entering of the elusive one for the entry of the first complementary amount into the accumulator by the machine, and means operating automatically thereafter to automatically enter elusive ones for all succeeding entries of complementary amounts into the accumulator.

97. The invention according to claim 50 wherein sensing means for special designations is provided for automatically calling into action an elusive one mechanism, said mechanism having provisions automatically controlled by the operations of the machine to omit the entering of the elusive one for the entry of the first complementary amount into the accumulator and thereafter controlled automatically to enter elusive ones for all succeeding entries of complementary amounts.

98. The invention according to claim 50 in which a special sensing means is provided for sensing designations in the record, with a plurality of accumulators and an elusive one entering mechanism, with means for selecting an accumulator to receive an entry under the control of the sensing means and for also controlling the action of the elusive one mechanism.

99. An accounting machine including in combination a plurality of record controlled accumulators including a balance accumulator receiving positive and negative entries and another accumulator arranged to receive entries from said balance accumulator upon

the clearing of said balance accumulator and card controlled means for clearing said balance accumulator automatically.

In testimony whereof I hereto affix my signature.
